UNITED STATES PATENT OFFICE

2,322,334

LEVELING MACHINE

Erastus E. Winkley, Lynn, Mass., assignor to
United Shoe Machinery Corporation, Flemington, N. J., a corporation of New Jersey

Application August 18, 1941, Serial No. 407,263

74 Claims. (Cl. 12—34)

This invention relates to machines for operating upon shoes, and more particularly to machines for shaping or leveling the bottoms of shoes. The invention is herein illustrated by reference to a leveling machine of the type disclosed in United States Letters Patent No. 1,667,761, granted on May 1, 1928, upon an application of Erastus E. Winkley and Herman A. Davenport, having a leveling tool, a shoe support and power-operated means for effecting relative movement of the shoe support and leveling tool in opposite directions lengthwise of the shoe to cause the leveling tool to operate along the shoe bottom in a predetermined cycle. Such machines are also provided with automatic means for pressing the leveling tool upon the shoe and for relieving the pressure at predetermined times in the cycle of operations of the machine and for imparting to the leveling tool tipping movements in opposite directions laterally of the shoe to cause the pressure of the tool to be applied at different inclinations in operating upon different portions of the shoe bottom. It is to be understood, however, that in its more general aspects the invention is not limited to use in machines of the particular type illustrated.

The present invention, in one important aspect, aims to provide improved means for controlling the power-operation of machines of the above-mentioned type, whereby the cycle of operations of the machine may be conveniently varied and determined as desired or as is necessary to meet varying conditions of work. For the purpose in view, as herein illustrated, there is provided a novel organization of power-operated means for effecting relative movements of the shoe support and leveling tool in opposite directions lengthwise of the shoe, other power-operated means for imparting to the leveling tool its tipping movements in opposite directions laterally of the shoe, and devices for controlling these power-operated means, one of which devices is arranged to determine the number and extent of the relative movements of the shoe support and leveling tool and also the time in each relative movement when the leveling tool begins its tipping movement and the other one of which is arranged to bring the power-operated means for tipping the leveling tool to a stop each time it is thus started after a tipping movement of predetermined extent in a predetermined direction has been imparted to the tool. Preferably and as illustrated, the controlling devices are so mounted that they may be readily and quickly removed and replaced by different devices for determining dif-

ferent cycles of operations of the machine. Thus the operator may by the use of the proper controlling devices cause the machine to operate automatically through a definite cycle best suited for the particular condition of work to be operated upon.

In a further aspect, the present invention provides novel mechanism for automatically controlling the power-operated means for effecting relative movements of the shoe support and leveling tool lengthwise of the shoe, comprising parts movable by the operator to start the power-operated means in operation and other parts operative in response to the relative movements of the shoe support and leveling tool for reversing the power-operated means at definite points in the operation of the tool on the bottom of the shoe and for bringing the power-operated means to a stop after a predetermined number of relative movements of the support and tool. In the construction herein shown, this mechanism includes the above-mentioned controlling device for determining the number and extent of the relative movements of the shoe support and the leveling tool, and a further novel feature of the invention is to be recognized in means provided for bringing the machine automatically to a stop after rearward and forward movements of predetermined extent have been imparted to the shoe support if the machine is inadvertently started when no controlling device is in the machine. The invention in its illustrative embodiment provides oppositely acting clutches through which the shoe support is moved in opposite directions, and also similar clutches for tipping the leveling tool, but it will be recognized that it is not thus limited since other means may be utilized for the accomplishment of the objects in view.

As a further feature, the invention provides novel means whereby the application of leveling pressure to the shoe bottom by the leveling tool is automatically controlled in such manner as to permit the leveling tool to be positioned heightwise of the shoe by engagement of the toe end of the shoe therewith before any substantial pressure is applied by the tool on the shoe bottom. In the construction herein shown, spring means is provided for pressing the leveling tool yieldingly down on the shoe, and automatic means for rendering the spring means thus effective on the tool only after the tool has been lifted by the shoe from an initial position lower than it occupies in operating upon the shoe into engagement with the bottom face of the toe

end of the shoe sole and for releasing the tool from the force of said spring means when the tool is again in that location on the shoe sole. More particularly, as herein illustrated, there are provided a pair of arms for transmitting force from the spring means to the leveling tool, a toggle connecting the arms, a stop arranged by engagement with one of the arms to hold the spring means under stress with the leveling tool released entirely from the force thereof, and a cam for moving the toggle into and out of a substantially straightened condition to render the spring means effective on the tool and to release the tool from the force of the spring means. Preferably and as illustrated, the cam is also so shaped as to cause the tool to be thus released each time in the relative movement of the shoe support and leveling tool when the leveling tool is located substantially at the junction of the forepart and shank portions of the shoe bottom. In accordance with another feature of the invention there is provided novel means for controlling the toggle independently of the above-mentioned cam to vary the times in the operation of the machine when the leveling tool is released from the force of the spring means. This means, in the construction shown, comprises a member for locking the above-mentioned arm against movement in the direction to engage the stop when released by the cam-operated toggle, and a device rotatable intermittently in time relation to the movements of the shoe support for operating the locking member at selected times to cause no pressure release of the tool to occur during predetermined movements of the shoe support.

The above and other features of the invention, including novel means whereby the leveling tool may be tipped continuously at a comparatively slow rate when the leveling tool is operating upon a selected portion of the shoe bottom, and various novel details of construction and combinations of parts, will now be more particularly described by reference to the accompanying drawings and pointed out in the claims.

In the drawings,

Fig. 32 is a section on the line XXXII—XXXII of Fig. 30.

55 Leveling machines of the type illustrated are twin machines comprising in their organization two sets of operating instrumentalities for operating respectively upon different shoes in different locations in the machine, each set comprising an automatically controlled leveling roll 50 (Fig. 1) and a shoe support or jack which in the power-operation of the machine is moved automatically in directions lengthwise of the shoe to cause the roll to operate progressively along the bottom of the shoe. For the purpose of an understanding of the present invention, reference will be made to only one of these two sets of instrumentalities, since it will be understood that, except as will appear hereafter, these two sets of operating instrumentalities are substantially duplicated in the opposite halves of the machine and mechanisms, such as illustrated as an embodiment of the invention, are provided for operating either or both sets of instrumentalities. It is further to be understood that in its more general aspects the

The pinion 436 meshes with segmental teeth formed on the end face of an arm 440 which is fulcrumed on the shaft 420. Pivotaly connected to the arm 440 is a link 442 having pivotally connected to its opposite end (Fig. 9) a block 444 which slidably engages a curved slot 446 formed in a normally stationary member 448 which is fulcrumed on a shaft 450 supported in bearings in the frame 56. The member 448 has formed thereon an upwardly extending portion 452 provided at its upper end with an elongated slot 454 into which extends a pin 456 projecting from the frame 56, and engaging the opposite sides of the pin 456 are adjustable screws 458 threaded in the upwardly extending portion 452 and held in adjusted position by locknuts 460. Fulcrumed on the shaft 450 is a bell-crank lever 462 one arm of which is connected by a link 464 to the link 442 and the other arm of which has pivotally connected to it a forwardly extending arm 466 provided with a hook-shaped end 468 (Fig. 3). A spring-pressed plunger 470 (Figs. 1 and 4) in the frame 56 tends by engagement with a lug 472 on the bell-crank lever 462 to swing the lever in a counterclockwise direction, as viewed in Fig. 1, the swinging movement of the lever in this direction being limited by the engagement of an adjustable screw 474 carried by the lever with a fixed abutment 476 on the frame 56. The above-mentioned arm 428 of the lever 432 has secured to it a segment worm gear 478 (Figs. 7 and 22) that meshes with a worm 480 fast on a shaft 482 mounted in suitable bearings in the bracket 158 in parallel relation to the above-mentioned shaft 156.

Power operated means, hereinafter described, is provided for rotating the worm 480 in opposite directions to impart tipping movements in opposite directions to the leveling rolls 50 through the above-described mechanism, and controlling mechanism, also hereinafter described, is provided for predetermining the times in the cycle of the machine when tipping movements are imparted to the leveling rolls and for also determining the direction and extent of such tipping movements. It will be understood that by reason of its connection to the member 448, the arm 440 is normally held against swinging movement so that, as the worm 480 is rotated to impart swinging movement to the lever 432 in either a forwardly or a rearwardly direction, the gears 424, 434 and 436 carried by the downwardly extending arms 428, 430 of the lever 432 are rotated by reason of the engagement of the gear 436 with the gear teeth formed on the arm 440. As the gear 424 is thus rotated, it acts to swing the lever 418 in a direction opposite to the direction of swinging movement of the lever 432 and, since the lever 412 is geared to the lever 418, the lever 412 is swung in the same direction as the lever 432. Forward swinging movement of the lever 432 will accordingly act through the above-described connections to the roll carrier 222 at the left-hand side of the machine to tip the roll 50 mounted on that carrier in a clockwise direction and, through the link 402, rock the carrier 222 at the right side of the machine in a direction to tip the roll mounted on that carrier in a counterclockwise direction. It will be evident that the directions of tipping movements of the leveling rolls in the opposite halves of the machine may be reversed by reversing the direction of rotation of the worm 480.

It will thus be seen that, as the roll is operating upon the forepart and shank portions of the

shoe bottom, tipping movements of different extent may be imparted to the roll to cause the pressure of the roll to be applied to the forepart and shank portions respectively at different inclinations properly to level them. Since the leveling roll is usually tipped at one inclination in operating in the forepart of the shoe and at one or more different inclinations in operating in the shank, the construction is preferably such that by rotation of the worm 480 the tipping movements of the roll are effected at a relatively rapid rate so that the inclination of the roll may be varied as desired in operating along these different portions of the shoe bottom. Since the leveling roll 50, as usual, is concaved slightly in the direction of its length, it is desirable in operating along the outer edge portion of the forepart of the shoe bottom that a continuous tipping movement at a relatively slow rate be imparted to the roll in order properly to level this portion of the forepart. For this purpose, there is provided means for releasing the above-mentioned arm 466 for movement into position to be connected to the jack-operating mechanism to cause the arm 440 to be swung relatively to the arm 432 to impart to the leveling roll a continuous tipping movement in response to the movement of the jack to cause the roll to traverse the outside edge portion of the forepart of the shoe bottom. As shown particularly in Figs. 3 and 22, there is fulcrumed on the shaft 210 a two-armed lever 484 which is connected by a bolt 486 to the above-mentioned arm 208 which forms one part of the jack-operating mechanism. The lever 484 has a depending arm 488 carrying a pin 490 which is arranged to be engaged by the hook-shaped end 468 of the arm 466 at the proper time in the operation of the machine. The arm 466 is normally held out of engagement with the pin 490 by an arm 492 (Figs. 1 and 4) the notched upper end portion of which engages a pin 494 projecting from the arm 466. The arm 492 is pivotally connected to the bracket 158 and formed integral with the arm 492 is a downwardly extending arm 498 connected by a forwardly extending link 500 to a lever arm 502 which is pivotally connected to a bracket 504 secured to the frame 56 by screws 506. Formed on the lever 502 is an inclined face 508, and arranged to engage this face is a pin 510 projecting from the edge face of the above-mentioned disk 374 (Figs. 3 and 5). At the proper time in the operation of the machine and preferably just prior to the forward swinging movement of the jack to cause the leveling roll to traverse the outside edge portion of the forepart of the shoe from the ball line forwardly to the toe end, the pin 510 acts by engagement with the inclined face 508 to swing the lever 502 in a clockwise direction (Fig. 1) to operate the arm 492 to release the arm 466 for downward movement into position to cause the pin 490 to engage the hook-shaped end 468 of the arm 466 and to exert a forward pull on the arm 466 in the forward swinging movement of the jack. As the arm 466 is thus moved forwardly, the bell-crank lever 462 is swung in a clockwise direction (Fig. 1) and, through the link 464, acts to swing the rear end portion of the link 442 upward relatively to the member 448. By reason of the curvature of the slot 446 in the member 448, the link 442 receives simultaneously a bodily forward movement to cause the arm 440 to be swung relatively to the lever 432. It will be understood that at this time in the operation of the machine the

worm 480 is stationary so that, as the arm 440 is thus swung relatively to the arm 432, it acts to rotate the gears 436, 434, and 424 and thus to tip the leveling rolls 50 at a comparatively slow rate during the forward swinging movement of the jack. It will be seen that by adjustment of the member 448 about the axis of the shaft 450 the inclination of the curved slot 446 may be varied to vary the rate of tipping movement of the roll in response to the forward swinging movement of the jack. As the jack is swung reversely, the pin 490 acts by engagement with an inclined surface 512 (Fig. 3) on the arm 466 to swing the arm upwardly into position to permit the notched arm 492 again to engage the pin 494 and thus to hold the arm 466 in its initially raised position, a spring 514 connected at one end to the arm 502 and at the other end to a pin 516 in the frame 56 acting to urge the arm 492 in the direction to engage the pin 494 as the pin 510 passes out of engagement with the inclined face 508 on the arm 502 which occurs just prior to the completion of the forward swinging movement of the jack.

For driving the shaft 156 and with it the worm 154 in opposite directions to impart rearward and forward swinging movements to the jack and to operate the cam 384 to control the leveling roll 50 automatically in the manner previously described, there are provided oppositely acting clutches 518, 520 (Fig. 12) the driving members of which are constantly rotated in opposite directions and the driven members of which are fast to the shaft 156. In the illustrated machine, power is derived from an overhead pulley (not shown) which, by means of a belt 522 (Fig. 1), drives a pulley 524 fast to the outer end of a shaft 526 journaled in the upper portion 528 of a two-part bracket 530 which is secured by screws 532 to the top of the frame 56. The belt 522 normally engages a loose pulley 534 on the shaft 526 and may be shifted into engagement with the pulley 524 by means of a shifter 536 which is slidably mounted on a rod 538 supported by the upper portion 528 of the bracket 530. The shifter 536 is connected by a link 538 to a split ring 540 which surrounds and is clamped to a second ring 542 rotatably mounted in a circumferential groove formed partly in the upper portion and partly in the lower portion of the bracket 530. The lower portion of the bracket 530 forms a bearing for the upper portion 528 which may be turned relatively to the lower portion to position the shaft 526 in parallel relation to the shaft on which the overhead driving pulley is mounted, a set screw 544 (Fig. 1a) being provided for holding the upper portion 528 in adjusted position relatively to the lower portion. The ring 542 is connected by a link 546 to a bracket 548 which is slidably mounted on a rail 550 supported by the lower portion of the bracket 530. Pivotedly connected to the bracket 548 is a hand lever 552 for moving the bracket 548 along the rail 550 to operate the belt shifter 536 by rotation of the rings 540, 542. The inner end portion of the hand lever 552 is formed to engage either a notch 554 in the rail 550 to hold the parts in the positions shown in Fig. 1 with the belt 522 engaging the loose pulley 534, or a notch 556 in the rail to hold the parts in the positions they assume when the belt is in engagement with the pulley 524. The outer split ring 540 is clamped to the inner ring 542 by means of a clamp screw 558. It will be seen that by loosening the screw 544 and the clamping screw 558 the upper portion 528 of the

bracket 530 and the parts supported thereby, including the belt shifter 536, may be turned relatively to the lower portion of the bracket 530 to position the shaft 526 in the desired relation to the overhead shaft and that, as the upper portion of the bracket is thus turned, the outer ring 540 turns with it so that it may be clamped to the inner ring 542 in any adjusted position of the upper portion 528 of the bracket 530 to establish an operative connection between the belt shifter 536 and the bracket 548.

Fast to the shaft 526 is a level gear 560 that meshes with a similar gear 562 fast to the upper end of a vertical shaft 564 that extends downwardly through an opening in the bracket 158 and has pinned to its lower end a bevel gear 566 (Fig. 12). The bevel gear 566 meshes with a bevel gear 568 which is bolted to a gear 570 pinned to a jack-shaft 572 mounted in suitable bearings in the bracket 158 in parallel relation to the shafts 156 and 482. Loosely mounted on the shaft 156 in spaced relation are a pair of gears 574, 576, the gear 576 being constantly rotated by a gear 578 pinned to the shaft 572. The gear 574 is constantly rotated in the opposite direction through an idler gear 580 (Fig. 14) which meshes with it and the gear 570 fast to the shaft 572. The gears 574, 576 are provided respectively, as shown, with laterally extending flanges 582, 584 which have internal clutch surfaces and act respectively as the driving members of the opposed clutches 518, 520. Cooperating therewith are driven members 585, 586 which are keyed to the shaft 156, the members 585 and 586 each carrying an expanding ring (not herein shown) and means comprising an arm 588 for expanding or contracting the ring to connect or disconnect the clutch members. Details of construction of the clutches 518, 520 are not herein shown, since they are substantially like that fully shown and described in Letters Patent No. 1,011,903, granted December 19, 1911, upon an application of A. Bates. For controlling the arms 588 to connect and disconnect the clutches 518, 520 there is keyed to the shaft 156 a sleeve 590. The sleeve 590 is moved lengthwise of the shaft to cause one or the other of the clutch members 585, 586 to be connected to its cooperating clutch member by a two-armed lever 592 which is fast to a bushing 594 on a rockshaft 595 supported in bearings in the bracket 158, the arms of the lever 592 straddling the sleeve 590 and carrying rolls 596 that extend into a circumferential groove 598 in the sleeve. Fast on the left-hand end of the bushing 594 (Fig. 15) is an upwardly extending forked arm 600 carrying rolls 602, and engaging the opposite sides of these rolls are the head portions 604 of sleeves 606, 608 slidably mounted on a forwardly and rearwardly extending rod 610 mounted for endwise movement in bearings in the frame 56 (Fig. 4). The forked arm 600 straddles a bushing 611 which is pinned to the rod 610 and acts as a spacer for the sleeves 606 and 608. Surrounding the sleeves 606 and 608 respectively are springs 612 and 614 that bear at one end against the heads 604 of the sleeves and at the opposite ends against adjustable collars 616 fast to the rod 610 and act normally to hold the arm 600 with the lever 592 in a centralized position with both clutches 518, 520 disconnected from the shaft 156 and with the machine at rest. It will be understood that by forward movement of the rod 610 the lever 592 may be swung in a direction to impart rearward movement to the sleeve 590 to cause the clutch 518 to

of the frame 56. The carrier 226 has a rearwardly extending arm 230 to which there is pivotally connected a block 232 slidably movable in a slot 234 formed in the rearwardly extending arm 236 of a bell-crank lever 238 fulcrumed at 240 to the top of the frame 56. The bell-crank lever 238 has a pair of downwardly extending arms 242, one of which is shown in Fig. 1, carrying trunnions 244 that extend into a circumferential groove 246 formed in a bushing 248 that is slidably mounted on the shaft 228. Pivotally mounted on a laterally extending shaft 250 supported by suitable bearings in the frame 56 is an upwardly extending arm 252 the upper portion of which is forked to straddle the bushing 248, the arms of the forked portion carrying trunnions 254 extending into a circumferential groove 256 in the bushing 248. When the machine is initially at rest, the roll 50 assumes a position somewhat lower than that which it occupies in operating upon the shoe, the roll being lifted against the weight of the parts by engagement of the toe end of the shoe therewith as the shoe supporting jack is swung rearwardly from jacking position into position to be connected to the arm 148. The initial position of the roll 50 is determined by engagement of a lug 258 on the arm 252 with an adjustable abutment, illustrated as a screw 260, which is threaded in the frame 56 and which may be adjusted to vary the lowermost position of the leveling roll. Pivotally connected to the arm 252 is one link 262 of a toggle the other link 264 of which is pivotally connected to a lateral projection on an arm 266 fulcrumed on the shaft 250. Pivotally connected to the arm 266 is an abutment 268 for a relatively heavy expansion spring 270 which bears at its lower end against an abutment 272 (Figs. 4 and 9) pivotally connected to one arm 274 of a lever 276 that is pivotally connected between two arms 278, one of which is shown in Fig. 1, fulcrumed on the shaft 210. The lever 276 has a second arm extending oppositely to the arm 274 and of the same length, to which there is pivotally connected an abutment 282 for a relatively heavy expansion spring 284 which bears at its upper end against an abutment 286 pivotally connected to the frame 56 (Fig. 1). The abutments 268, 272 and 282, 286 are each provided with a reduced central portion 288 (Fig. 9) surrounded by the end portions of the springs 270 and 284, the reduced portions 288 acting to centralize the springs relatively to the abutments.

It will be evident that the springs 270, 284 tend to swing the arm 266 in a clockwise direction (Fig. 1), the swinging movement of the arm in this direction being limited by the engagement of an adjustable abutment, illustrated as a screw 290 carried by the arm with a lug 292 on the frame 56. The toggle links 262, 264 are pivotally connected to each other and to a third link 294 which is pivotally connected at its lower end to one arm of a bell-crank lever 296 fulcrumed on a shaft 298 supported by suitable bearings in the frame 56. The bell-crank lever 296 has a second arm 300 carrying a roll 302 arranged to engage a cam 304 formed on the end face of an arm 306 which is formed integral with the above-mentioned arms 208 and 212 fulcrumed on the shaft 210. Formed integral with the above-mentioned arms 278 are a pair of rearwardly extending arms 308, one of which is shown in Fig. 4, and pivotally connected to the arms 308 are upwardly extending links 310 between which is pivotally connected a block 312 threaded to re-

ceive a vertical rod 314. At its upper end the rod 314 is rotatably mounted in a bearing 316 in the frame 56, and at its lower end the rod has a reduced portion which is rotatably mounted in a bearing 318 secured to the frame 56 by screws 320. Fast to the rod 314 is a worm gear 322, the hub of which bears against the bottom face of the bearing 316 and the teeth of which mesh with a worm 324 fast to a laterally extending shaft 326 mounted in suitable bearings in the frame 56 and having fast to its outer end a hand wheel 328 for turning it. It will be evident that by rotating the hand wheel 328, the rod 314 may be rotated to move the boss 312 heightwise in the machine and, through the links 310 and arms 308, to swing the arms 278 in directions to vary the tension of the springs 270, 284.

At a predetermined time in the rearward swinging movement of the jack, as more particularly hereinafter described, and after the roll 50 has been lifted by engagement of the toe end of the shoe therewith, the arm 306 is swung in a counterclockwise direction, as viewed in Fig. 1. The shape of the cam face 304 is such that, as the arm 306 is thus swung, the bell-crank lever 296 receives a swinging movement in a counterclockwise direction and, through the link 294, moves the toggle links 262, 264 into substantially parallel relation to each other. Straightening of the toggle 262, 264 causes the arm 266 to be swung in a counterclockwise direction to move the adjusting screw 290 out of engagement with the lug 292 against the resistance of the springs 270, 284 which act thereafter to press the leveling roll 50 yieldingly against the bottom of the shoe.

In the power operation of the machine, the arm 306 receives a swinging movement in a counterclockwise direction (Fig. 1) and then in a clockwise direction in time relation to the rearward and forward swinging movements of the jack. The shape of the cam face 304 is such that after the bell-crank lever 296 has been swung in the direction to straighten the toggle 262, 264 to cause the leveling roll to be pressed yieldingly against the bottom of the shoe substantially at the beginning of the first rearward swinging movement of the jack, the bell-crank lever 296 is permitted to be swung reversely by the action of the springs 270, 284 on the arm 266 to break the toggle 262, 264 and thus to cause a full release of the pressure of the roll on the shoe bottom substantially at the time when the roll is located at the junction of the forepart and shank portions of the shoe bottom. Thereafter, in the continued rearward swinging movement of the jack, the bell-crank lever 296 is again swung in the direction to straighten the toggle 262, 264 to cause the roll to be pressed yieldingly against the bottom of the shoe as the roll traverses the shank portion of the shoe bottom. As the arm 306 is swung reversely in time relation to the forward swinging movement of the jack, the full release of the pressure of the roll occurs when the roll is again substantially at the junction of the forepart and shank portions of the shoe bottom. Thus, in the control of the toggle 262, 264 by the cam 304, the pressure relief of the leveling roll occurs each and every time in the rearward and forward swinging movement of the jack when the roll is located substantially at the junction of the forepart and shank portions of the shoe bottom, the shape of the cam 304 being such as to cause the pressure to be relieved gradually as the roll approaches the

junction of the forepart and shank portion in either direction and to be fully relieved when the ball line of the shoe is under the leveling roll.

In order to prevent any relief of pressure of the leveling roll on the shoe bottom, or to cause the pressure relief to occur only in predetermined rearward or forward swinging movement of the jack, the illustrated machine is provided with means for controlling the toggle 262, 264 independently of the cam 304. This means comprises a latch 330 (Fig. 1) loosely mounted on the shaft 250 and arranged by engagement with a notched arm 332 on the cam lever 296 to hold the cam lever against swinging movement in the direction to break the toggle 262, 264 when permitted to do so by the cam 304. For controlling the latch 330, there is provided a rod 334 the L-shaped upper end of which is secured to a block 336 which is pivotally connected to a rearwardly extending arm 338 on the latch 330, and mechanism for operating the rod to move the latch automatically into and out of latching engagement with the notched arm 332 at predetermined times in the cycle of the machine. As shown particularly in Figs. 1 and 4, the rod 334 is vertically movable in a boss 340 formed at the upper end of an arm 342 pivotally connected at its lower end to one arm of a lever 344 which is pivotally connected to a bracket 346 secured to the frame 56 by screws 348 (Fig. 5). The lever 344 has a second arm 350 that extends oppositely to the first arm and is connected by a link 360 (Fig. 1) to an arm 362 fast to a forwardly and rearwardly extending shaft 364 mounted in suitable bearings in the frame 56 of the machine. Fast to the forward end of the shaft 364 is a two-armed lever 366, the arms 370, 372 of which straddle a disk 374 which is secured to the outer end of a shaft 376 mounted in bearings in the frame 56. The disk 374 is indexed through one complete rotation in the direction indicated by the arrow in Fig. 5, by means hereinafter described, in each cycle of operations of the machine, and projecting from the front face of the disk 374 are pins 378 arranged by engagement with the arm 370 to swing the lever 366 in a clockwise direction (Fig. 5). Projecting from the rear face of the disk 374 are pins 380 arranged by engagement with the arm 372 to swing the lever 366 in a counterclockwise direction. Surrounding the above-mentioned rod 334 at opposite sides of the boss 340 are springs 382, 384 (Figs. 1 and 4). The spring 382 bears at its upper end against an adjustable collar 386 secured to the rod 334 and at its lower end against a washer 388 that engages the upper face of the boss 340. At its upper end the spring 384 bears against a washer 390 that engages the bottom face of the boss 340, and at its lower end the spring bears against an adjustable collar 392 fast on the rod 334.

It will be evident that, as the lever 366 (Fig. 5) is swung in a clockwise direction, upward movement is imparted to the arm 342 and that, as the lever is swung in a counterclockwise direction, downward movement is imparted to that arm. When the machine is initially at rest, the springs 382, 384 act to hold the rod 334 in the position indicated in Fig. 1 with the latch 330 in an inoperative position to permit free swinging movement of the lever 296 and the arm 332. Upward movement of the arm 342, however, acts to compress the spring 382 and, through the rod 334, to swing the latch 330 into position to engage the notched arm 332 and to hold the lever 296 against

swinging movement in the direction to break the toggle 262, 264. Downward movement of the arm 342 will act to compress the spring 384 and, through the rod 334, swing the latch 330 in the direction to withdraw it from latching position. As previously pointed out, a rise 394 in the cam 304 acts to swing the lever 296 in a clockwise direction (Fig. 1) to straighten the toggle 262, 264 substantially at the beginning of the power 10 operation of the machine, after which a depression 396 in the cam permits the lever 296 to be swung reversely to break the toggle, the full release of the pressure of the roll 50 on the shoe bottom occurring substantially at the time when 15 the ball line of the shoe is under the leveling roll. Thereafter the lever 296 is again swung in the direction to straighten the toggle by the rise 398 in the cam as the roll traverses the shank portion of the bottom of the shoe from the ball line toward the heel end. The rise 394 and the rise 398 are effective to swing the lever 296 in a clockwise direction far enough to permit the latch 330 to be moved freely either into or out 20 of latching engagement with the notched arm 332. Accordingly, by means of the pins 378, 380, the latch 330 may be moved into latching engagement with the notched arm 332 substantially at the beginning of the cycle of the machine and moved out of that relation to the arm 332 substantially at the end of the cycle so as to cause no pressure relief of the leveling roll to occur during the leveling operation, or the arrangement of the pins may be such as to cause a relief of pressure to occur only during predetermined 25 rearward or forward swinging movements of the jack.

The roll carriers 222 are mounted for rocking movements about the axes of the shaft 228 to impart to the leveling rolls 50 their tipping movements laterally of the shoe at various inclinations for operating along the opposite edges of the shoe bottom. It is contemplated that right and left shoes will be operated upon in the opposite halves of the machine and, accordingly, the carriers 222 are each provided with a laterally extending arm 400 (Fig. 2), the arms being connected by a link 402 so that equal tipping movements in opposite directions will be imparted to the leveling rolls 50. For imparting to the roll carriers 222 their rocking movements, there is pivotally connected to a laterally extending projection 404 on the carrier 222 at the left-hand side of the machine a block 406 to which there is pivotally connected an extensible link 408 which is pivotally connected at its lower end to a block 409 rotatably mounted on a stud 411 carried by one arm 410 of a bell-crank lever 412 (Figs. 7 and 9) fulcrumed on the shaft 210. The bell-crank lever 412 has a second arm 414 on the edge face of which are formed segmental teeth that mesh with similar teeth formed on the edge face of an arm 416 formed on a lever 418 which is fulcrumed on a shaft 420 supported at one end by a bearing in the bracket 56. The lever 418 has a downwardly extending arm 422 on which are formed segmental teeth that mesh with the teeth of a pinion 424 which is pinned to a shaft 426 rotatably mounted in bearings formed in the downwardly extending arms 428, 430 (Fig. 22) of a lever 432 also fulcrumed on the shaft 420. Fast to the shaft 426 is a second pinion 434 (Figs. 22 and 23) that meshes with a pinion 436 pinned to a shaft 438 supported in bearings in the arms 428, 430 in parallel relation to the shaft 426.

be connected to the shaft 156 to rotate it in the direction to impart rearward swinging movement to the jack, and by rearward movement of the rod 610 forward movement may be imparted to the sleeve 590 to disconnect the clutch 518 from the shaft 156 and to connect the clutch 520 to the shaft to reverse the direction of swinging movement of the jack.

Fast to the forward end of the rod 610 is a block 618 (Figs. 3 and 5) to which there is pivotally connected the upwardly extending arms 620 of a bell-crank lever 622 pivotally connected to the bracket 504. The bell-crank lever 622 has a pair of forwardly extending arms carrying pins 624 that extend into an elongated slot 626 formed in the upper end of a link 628 pivotally connected at its lower end to a treadle 630 fulcrumed at 632 to the frame 56. By depressing the treadle 630, forward movement may be imparted to the rod 610 to swing the arms 600 (Figs. 4 and 15) and, through the bushing 594, the lever 592 in the direction to cause the clutch 518 to be connected to the shaft 156 and to rotate the shaft in the direction to impart rearward swinging movement to the shoe-supporting jack. It will be understood that the rod 610 may thereafter be moved rearwardly to swing the lever 592 in the direction to impart forward movement to the sleeve 590 to disconnect the clutch 518 and to connect the clutch 520, thus causing the jack to be swung in a forward direction.

In the illustrated machine, the direction and extent of each swinging movement of the shoe-supporting jack are determined automatically by means of a controlling device 633 (Fig. 26) and connections therefrom to the rod 610. Fast to the rod 610 is a block 634 (Fig. 3), and engaging the opposite side faces of the block 634 are sleeves 636, 638 slidably mounted on the rod. The sleeves 636, 638 are surrounded respectively by equal springs 640, 642 which bear at one end against the heads 644 of the sleeves and at their opposite ends against adjustable collars 646 fast to the rod 610. Pivotedly connected to the bracket 504 are oppositely acting latches 648, 650 between which there extends a spring 652 which tends to impart downward swinging movement to the latches. The latches are upheld, when the machine is initially at rest, against the resistance of the spring 652 by a roll 654 on the block 634. As the block 634 is moved forwardly with the rod 610 in response to depression of the treadle 630, the roll 654 passes out from under the pawl 650, thereby releasing this pawl to the action of the spring 652 for downward swinging movement into engagement with the head 644 of the sleeve 638 in which position the pawl 650 acts as an abutment for the roll 654 to lock the rod 610 in its forward position with the friction clutch 518 connected to the shaft 156. With the clutch 518 thus connected, the arm 208 is swung rearwardly to impart rearward swinging movement to the jack, and movable with the arm 208 is the above-mentioned two-armed lever 484 (Figs. 3 and 22), a downwardly extending arm 656 of which carries a pin 658 arranged to extend into a circumferential groove 670 in a sleeve 672 which is slidably mounted on a shaft 674 which at its rear end is supported in a bearing in the bracket 158 (Fig. 4), a set screw 675 being provided for holding the shaft against endwise movement and also against turning movement. Mounted on the forward end of the shaft 674 is a disk 676 (Fig. 26) which is fitted to slide in a bore 678 in the bracket 504. Formed integral

with the sleeve 672 is a gear 680, and surrounding the shaft 674 forwardly of the gear 680 is a bushing 682 the opposite end portions of which are recessed to receive the hub portions of the disk 676 and a second disk 684 connected by a shoulder pin 685 to the gear 680, the two disks 676 and 684 being thus held in predetermined spaced relation by the bushing 682. Pinned to the sleeve 672 is a tongue 686 (Fig. 27) which extends forwardly in a groove 688 in the bushing 682 and has formed on its forward end a head 690 that acts by engagement with the front face of the disk 676 to hold the disks 676, 684 and the bushing 682 in assembled relation on the shaft 674. Slidably mounted on the bushing 682 are sleeves 692, 694 (Fig. 26) on which are formed respectively flanges 696 and 698 each of which is provided with a plurality of spaced notches or slots, as shown particularly in Fig. 28, to receive finger pieces 700. The finger pieces 700 are each recessed at one end to straddle one of the flanges 696, 698 and are each fitted to slide in a slot in the other flange. The several fingers are held in the slots by split rings 702, 704 that surround the flanges and are secured thereto by screws 706. The sleeves 692, 694 are adjustable along the bushing 682 by means of rods 708, 710 (Fig. 28) that are rotatably mounted in the disks 676, 684, the rod 708 being threaded in the flange 696 and extending through an enlarged opening in the flange 698, and the rod 710 extending through an enlarged opening in the flange 698 and being threaded in the flange 696. Each rod is held against endwise movement relatively to the disks 676, 684 by the engagement of a shoulder 712 on the rod with one face of the disk 684 and the engagement of a collar 714 pinned to the rod with the inner face of the disk 676. At their forward ends the rods 708, 710 are shaped for engagement with a socket wrench so that they may be rotated to adjust the sleeves 692, 694 respectively along the bushing 682.

Extending downwardly through an elongated slot 716 in the bracket 504 at right angles to the axis of the shaft 674 is a pin 718 carried by an arm 720 pivotally connected to the bracket 504 (Fig. 5). The pin 718 extends upwardly from the arm 720 between the head portions 644 of the sleeves 636 and 638 that are slidably mounted on the rod 610, and surrounding the upwardly projecting portion of the pin is a roll 722. When the machine is initially at rest, the pin 718 is in engagement with the inner face 724 of the disk 684. As the arm 208 is swung rearwardly to impart to the jack its first rearward swinging movement, the sleeve 672 and the bushing 682 and the parts assembled thereon are moved rearwardly along the shaft 674 by the arm 656. At this time the positions of the finger pieces 700 are such that, as the bushing 682 is thus moved, the pin 718 is finally engaged by the disk 676, and the arm 720 swung rearwardly. As the arm 720 is thus swung, the roll 722 moves the sleeve 638 rearwardly along the rod 610 to compress the spring 642 until the head 644 of the sleeve acts by engagement with an inclined face on the latch 650 to swing it upwardly far enough to carry it out of engagement with the roll 654. The springs 640, 642 are considerably heavier than the springs 612, 614 so that, as the rod 610 and the block 634 are released by the latch 650, the spring 642 moves the rod 610 and the block 634 rearwardly. The lever 592 is accordingly swung in the direction to impart forward move-

ment to the sleeve 590 to cause the clutch 518 to be disconnected from, and the clutch 520 to be connected to, the shaft 146, the latch 648 being swung at the same time by the spring 652 into position to act as an abutment for the roll 654 to lock the rod 610 against forward movement with the clutch 520 connected to the shaft 156.

The forward and rearward movements of the rod 610 to control the direction of swinging movement of the jack are controlled automatically by engagement of the pin 718 with the disk 676 or the heads of shoulder pins 724 in the disk 684 or with one of the finger pieces 700, the sleeve 682 and the parts assembled thereon being rotated intermittently about the axis of the shaft 674 to bring different finger pieces 700 or pins 724 successively into position to engage the pin and to act through the above-described connections to reverse the direction of swinging movement of the jack at definite points in the operation of the roll 50 on the bottom of the shoe. As previously pointed out, the disks 676 and 684 and the sleeve 682 are moved rearwardly along the shaft 674 in response to the first rearward swinging movement of the jack and, since in the illustrated construction none of the finger pieces 700 is at this time in position to engage the pin 718, the jack continues to swing rearwardly until the disk 676 engages the pin 718 and, through the above-described connections, causes the rod 610 to be moved rearwardly and the clutch 518 to be disconnected from, and the clutch 520 to be connected to, the shaft 156. The shaft 156 is rotated in a direction to impart forward swinging movement to the jack the extent of which is limited by engagement of the pin 718 either with a finger 726 on one of the finger pieces 700 or with the head of one of the shoulder pins 724 in the disk 684, each pin 724 acting to limit the forward swinging movement of the jack with the leveling roll engaging the bottom face of the toe end of the sole in such a location as to avoid any excessive bending of the margin of the sole yet near enough to the end of the toe to permit proper leveling of the toe portion of the sole. Thereafter, as the jack is again swung rearwardly, the extent of its rearward swinging movement is limited by engagement of the pin 718 either with the disk 676 or with a finger 725 on one of the finger pieces 700. By reference to Figs. 28 and 29, it will be seen that the arrangement of the finger pieces 700 is such that the cycle of operations of the machine comprises first a rearward movement of the jack to cause the roll 50 to traverse the shoe from the toe end to the heel seat, then a plurality of backward and forward movements while the roll is operating in the shank, thereafter a movement to cause the roll to return to the forepart along one side, and then a backward and forward movement while the roll is operating along that side of the forepart, after which the roll again traverses the shoe from the toe end to the heel seat, followed by a plurality of backward and forward movements to cause the roll to operate in the shank at that side of the shoe, then a plurality of rearward and forward movements in the forepart on the same side of the shoe, followed by a movement to cause the roll to return to the toe end, after which the roll traverses the shoe from the toe end substantially to the junction of the forepart and shank, and finally a movement to cause the roll to return to the toe end and to leave the shoe.

For rotating the disks 676, 684 and the sleeve 682 to bring the different finger pieces 700 and the shoulder pins 724 successively into position to engage the pin 718, there is provided a pinion 5 728 (Fig. 26) the teeth of which mesh with the teeth of the gear 680 on the sleeve 672 and with the teeth of a gear 730 (Fig. 3) fast on the shaft 376. Loosely mounted on the shaft 376 is a grooved pulley 732 which is constantly driven 10 by means of a belt 734 from a grooved pulley 736 fast to the outer end of the jack-shaft 572 (Fig. 4). Formed integral with the pulley 732 is a disk 738 the edge face of which is formed as 15 shown in Fig. 24 with a plurality of recesses 740 and lands 742. Fast to the shaft 376 is a disk 744 to which there are pivotally connected a plurality 20 of levers 746 carrying rolls 748 yieldingly held in engagement with the edge face of the disk 738 by spring-pressed plungers 750 in the hub portion of the disk 744 engaging inwardly extending arms 25 752 on the levers 746. Keyed to the shaft 376 are two ratchet wheels 754, 756 (Figs. 3 and 25), and pivotally connected to the bracket 504 at 758 are two pawls 760, 762 (Fig. 25) arranged respectively to cooperate with the ratchet wheels 754, 30 756 to hold the shaft 376 against rotation. The pawl 762 has formed thereon a tail portion 764 which is connected by a link 766 to one end of a lever 768 the opposite end portion of which is connected by a link 770 to the pawl 760. Intermediate between its ends the lever 768 is pivotally connected to a link 772 which extends upwardly and is pivotally connected at its upper end to the rearwardly extending arms 774 (Fig. 3) on 35 the bell-crank lever 620. It will be evident that the continuously driven member 738 tends constantly through the levers 746 and disk 744 to rotate the shaft 376 in a clockwise direction (Figs. 24 and 25). The shaft 376 is held against rotation initially by engagement of the pawl 760 with the ratchet wheel 754. As the rod 610 is moved 40 forwardly to start the power operation of the machine in response to swinging movement of the bell-crank lever 620 in a counterclockwise direction (Figs. 1 and 3) by depression of the treadle 630, the link 772 is moved upwardly and, by reason of the frictional engagement of one of the teeth 776 of the ratchet wheel 754 with the end of the pawl 760, the lever 768 is first 45 50 swung about its pivotal connection to the link 770 in the direction to swing the pawl 762 downwardly into engagement with the ratchet wheel 756 between two of its teeth 778, after which the lever 768 is swung reversely about its pivotal connection to the link 766 to move the pawl 760 upwardly out of engagement with one of the ratchet teeth 776. As the pawl 760 is thus moved, the shaft 376 is rotated in a clockwise direction 55 (Fig. 25) until one of the ratchet teeth 776 engages the end of the pawl 762. Thereafter as the lever 620 is swung in a clockwise direction in response to rearward movement of the rod 610, the link 772 is moved downwardly to move the pawl 760 into position to engage one of the ratchet teeth 776, after which the pawl 762 is moved out of engagement with one of the ratchet teeth 778. The shaft 376 is accordingly rotated 60 65 intermittently in time relation to the forward and rearward movements of the rod 610 and, through the above-described gearing, acts to rotate the controlling device 633 comprising the disks 676, 684 and the finger pieces 700, step by step, about the axis of the shaft 674. It will be understood also that the pin disk 374 fast to the shaft 376 70 75 is thus indexed through one complete rotation

and through the mechanism previously described controls the time or times in the cycle of the machine when the relief of pressure of the leveling roll 50 on the shoe bottom occurs.

The illustrated machine is further provided with means for automatically reversing the direction of swinging movement of the shoe-supporting jack if the controlling device 633 is not in the machine and the machine has been accidentally started by depression of the treadle 630. For this purpose there is carried by the arm 488 of the two-armed lever 484 (Figs. 1 and 22) a roll 780 which, at a predetermined time in the rearward movement of the jack and preferably when the leveling roll is located farther heelwardly than the junction of the shank and heel end portions of the shoe bottom, is arranged to engage a shoulder 782 (Fig. 22) on a link 784 pivotally connected to the arm 720. At its opposite end the link 784 is pivotally connected to an arm 785 fulcrumed on the bracket 153 (Fig. 4). Engagement of the roll 780 with the shoulder 782 acts through the link 784 to swing the arm 720 in the direction to cause the spring 642 to be compressed and the latch 650 to be lifted to release the rod 610 for rearward movement to disconnect the clutch 518 from the shaft 156 and to connect the clutch 520 to the shaft 156 and thus to cause the jack to be swung forwardly. Carried by the arm 656 of the lever 484 is an adjustable screw 786 the head of which in the forward movement of the jack is arranged to engage and swing a small bell-crank lever 787 pivoted at 789 to the bracket 504. One arm of the bell-crank lever 787 engages a pin 788 (Fig. 3) projecting from the latch 648 so that as the bell-crank lever is thus swung it operates the latch 648 to release the rod 610 for forward movement. As the rod 610 moves forwardly it is centralized by the springs 640, 642 with the block 634 in its initial position, the latches 648, 650 being upheld by the roll 654 and the clutches 518, 520 disconnected from the shaft 156. The latch 648 is thus operated substantially at the time in the forward movement of the jack when the toe end of the shoe is moved out from under the leveling roll 50 and the spring-operated pin 150 is withdrawn to disconnect the jack from the arm 148. Accordingly, if the machine is accidentally started with no controlling device 633 in the machine, the jack receives merely a rearward and forward swinging movement after which it is disconnected from its operating arm 148 to permit it to return to its initial starting position.

In the illustrated construction, the power-operated means for rotating the shaft 482 and the worm 480 in opposite directions to impart to the leveling roll 50 its tipping movements in opposite directions comprises a pair of oppositely acting clutches not herein shown in detail since they are identical with the clutches 518, 520 for driving the shaft 156 and the worm 154 in opposite directions to impart rearward and forward swinging movements to the shoe-supporting jack. The driving member of the forward clutch similar to the member 582 of the clutch 518 for the shaft 156 has formed integral with it a gear 790 (Fig. 14) that meshes with the idler gear 580, and the driving member of the rear clutch similar to the member 584 of clutch 520 has formed integral with or secured to it a gear 792 the teeth of which mesh with the continuously driven gear 570 on the shaft

582. It will be understood that these clutches are provided with driven members keyed to the shaft 482 similar to the driven members 595, 596 of the clutches 518, 520 and that these driven members each have an expanding ring and means comprising arms similar to the arms 588 of the clutches 518, 520 for expanding or contracting the rings to connect or disconnect the clutch members. For controlling the arms 588 there is keyed to the shaft 482 a sleeve 794 (Fig. 11) similar to the sleeve 590 for controlling the arms 588 of the clutches 518, 520 and straddling this sleeve is a two-armed lever 796 the arms of which carry rolls 798 extending into a circumferential groove 800 in the sleeve 794. The lever 796 is fast to the shaft 595 which, as previously pointed out, is supported in bearings in the bracket 153.

In the machine herein shown, the time or times in the swinging movements of the shoe-supporting jack when the leveling roll 50 is tipped laterally of the shoe, is determined by the device 633 while the direction and extent of each tipping movement of the leveling roll are determined by a second device 802 illustrated particularly in Figs. 30, 31 and 32. Loosely mounted on the left-hand end of shaft 595 (Fig. 11) is a forked lever 804 which straddles a second lever 806 pinned to the shaft 595. The lever 806 (Fig. 9) has a pair of downwardly extending arms carrying centers 808 which support a shaft 810 the intermediate portion 812 of which is of larger diameter than the oppositely extending end portions of the shaft. Engaging the shoulders thus formed by the intermediate portion 812 and the end portions of the shaft 810 are washers 814 held against the shoulders by comparatively heavy compression springs 816 which surround the end portions of the shaft and bear at their opposite ends against adjustable collars 818 clamped to the shaft. Carried by the downwardly extending arms 820, 822 of the forked lever 804 are rolls 824 that extend between and engage the inner faces of the washers 814 and carried by the forked lower end of the arm 820 is a roll 826, which is arranged to be engaged by one or the other of a pair of upwardly extending arms 828, 830. Each arm 828, 830 has an inclined inner face 831 and at the proper time in the cycle of the machine the arms 828, 830 are moved upwardly with one of them in position to engage the roll 826 and to swing the lever 804 either in a clockwise direction or in a counterclockwise direction, as viewed in Fig. 9, a roll 832 being provided for supporting each arm 828, 830 as it is moved upwardly to impart swinging movement to the lever 804. It will be understood that swinging movement of the lever 804 in a clockwise direction will cause the lever 806 through one of the springs 816 to be swung in the same direction to impart clockwise rotation to the shaft 595 (Fig. 9), and that swinging movement of the lever 804 in a counterclockwise direction will cause the shaft 595 to be rotated in a counterclockwise direction. Clockwise rotation of the shaft 595 will cause the sleeve 794 to be moved in one direction along the shaft 482 to cause one of the friction clutches to be connected to the shaft 482 and the leveling roll to be tipped in one direction laterally of the shoe, and counterclockwise rotation of the shaft will cause movement of the sleeve in the opposite direction to cause the other friction clutch to be connected to the shaft 482 and the leveling roll

tipped in the opposite direction laterally of the shoe. The arms 828, 830 are pivotally connected between the inwardly extending arms 834 of a forked lever 836 fast to a shaft 840 supported in a suitable bearing in the frame 56 of the machine (Fig. 9). Springs 842 extending between the arms 828, 830 and the arms 834 of the lever 836 tend to hold the arms 828, 830 in engagement respectively with upwardly extending arms 844, 846, the arm 844 being clamped to a shaft 850, and the arm 846 being clamped to a bushing 848 surrounding the shaft 850. The shaft 850 is supported partly by a bearing in the bracket 158 and partly by a bearing in a bracket 852 secured to the frame 56 by screws 854 (Fig. 7). Clamped to the bushing 848 is a second arm 856 (Figs. 7 and 8) connected by a pair of links 858 to a downwardly extending arm 860 formed on a horizontal bar 862 pivoted at 864 to the bracket 852. Fast to the shaft 850 is an arm 866 connected by a pair of links 868 to the downwardly extending arm 870 formed on a second horizontal bar 872, also pivoted at 864 to the bracket 852. Springs 874 (one of which is shown in Fig. 10) extending between pins 876 in the frame 56 and the arms 856, 866 tend normally to hold the bars 862, 872 in engagement with a shoulder 878 on the bracket 852 (Fig. 31) with both arms 828, 830 out of operative relation to the roll 826 carried by the arm 820 of the lever 804.

As more particularly hereinafter described, the control device 802 is arranged to operate either bar 862, 872 to move either arm 828, 830 into operative relation to the roll 826 to determine the direction of tipping movement of the leveling roll, the arms 828, 830 being moved upwardly, however, with either one in operative relation to the roll 826 by mechanism controlled by the device 633 so that the leveling roll will begin its tipping movement in time relation to the swinging movement of the shoe supporting jack. For this purpose there is pivotally connected to a downwardly extending arm 880 of the lever 836 (Fig. 11) an adjustable rod 882 which is pivotally connected at its opposite end to an arm 884 fulcrumed on a stud 886 carried by a bracket 888 (Figs. 17 and 18) secured to the rear face of the bracket 158. The arm 884 carries a roll 890 engaging the concaved end face of one arm of a bell crank lever 892 which is pivotally connected to the bracket 888 at 894 and has a downwardly extending arm 896 carrying a pin 898 extending into a recess 900 formed in the left-hand end portion (Figs. 6 and 18) of a link or bar 902 pivotally connected at its opposite end to a downwardly extending arm 904 (Fig. 17) fast to a rockshaft 906 supported in bearings in the bracket 594. Mounted to turn about the axis of a short vertical shaft 908 (Fig. 5) supported in bearings in the bracket 504 is a lever 910 having oppositely extending arms one of which is shown at 912 (Fig. 5) and engaging the arms 912 are upwardly extending arms one of which is shown at 914 (Fig. 5), the arms 914 being secured to the rockshaft 906. The lever 910 has an inwardly extending central arm or pin 916 and formed in the flanges 696, 698, respectively, of the sleeves 692, 694 of the control device 633 are notches or slots to receive finger pieces 918 (Fig. 28) similar to the finger pieces 700 of that device. It will be evident that, as the device 633 is moved lengthwise of the shaft 674 in response to the swinging movement of the shoe supporting jack, when a projection or finger on one of the finger pieces

918 engages the pin 916 carried by the lever 910, the lever will be rotated about the axis of the shaft 908 and by engagement of one of its arms 912 with one of the arms 914 on the rockshaft 5 908 the arms 914 will be swung always in a counterclockwise direction, regardless of the direction of rotation of the lever 910. Similarly, engagement of either the disk 676 or the head of a shouldered pin 724 in the disk 684 will cause 10 counter-clockwise rocking movement to be imparted to the shaft 906.

Surrounding the above-mentioned adjustable rod 882 (Fig. 11) is an expansion spring 920 which bears at one end against a boss 922 on the frame 56, through which boss the rod 882 extends loosely, and at the other end the spring bears against an adjustable collar 924 fast to the rod 882. The spring 920 tends to move the rod 882 to the right (Fig. 11) and to impart swinging movement to the bell crank lever 836 in the direction to move the arms 828, 830 upwardly when permitted to do so by release of the rod 882 and the arm 884. This is effected each time in the swinging movement of the shoe supporting jack 25 when the lever 910 (Fig. 5) is swung about the axis of its shaft 908 to impart counterclockwise rotation to the rockshaft 906 (Fig. 6), the arm 904 being then swung in a direction to pull the bar 902 to the right (Fig. 6) and by engagement 30 of the link with the pin 898 carried by the arm 896 to swing the bell crank lever 892 in the direction to release the arm 884 and the rod 882 to the action of the spring 920.

For returning the parts to their initial starting 35 positions and for reloading the spring 920 there is provided mechanism which will now be described. Carried by the arm 884 is a spring-pressed plunger 926 (Fig. 17) which tends normally to hold a finger 928, pivotally connected to one arm 930 of a bell crank lever 932 loosely mounted on the stud 886, in the position indicated in Fig. 18. A spring 934 extending between the finger 928 and the hub of the bell crank lever 932 acts to hold the finger in engagement with the plunger 926. The bell crank lever 932 has a depending arm 936 carrying a pin 938 which extends into a slot 940 formed in the upper end of an arm 942 pivotally connected to the rod 882. Extending between the bell crank lever 50 932 and the arm 896 of bell crank lever 892 is a spring 944 that tends to swing the bell crank lever 892 in the direction to hold it in engagement with the roll 890 on the arm 884 and also to swing the bell crank lever 932 in the direction to hold it in engagement with an adjustable stop 55 illustrated as a pin 946 projecting downwardly from the bracket 888. Release of the arm 884 and the rod 882 to the action of the spring 920 in response to counterclockwise swinging movement of the bell crank lever 892 (Fig. 18), permits the spring 920 to move the rod 882 to the right and to impart counterclockwise swinging movement to the arm 884. As the rod 882 is thus moved the arm 942 first engages a shoulder 948 60 on the bell crank lever 892 and by reason of its slot-and-pin connection 938, 940 with the bell crank lever 932 it acts thereafter to swing the bell crank lever 932 in a direction to lower the finger 928. It will be understood that in response to counterclockwise swinging movement of the arm 884 (Fig. 18) the finger 928 also swings counterclockwise with the arm 884 as it is thus lowered. Accordingly the finger 928 is into position 65 to be engaged by the notched lower end of a bar 950. Counterclockwise swinging movement of

the arm 884 is limited by the engagement of a projection 952 on the arm with the depending arm 936 of the bell crank lever 932. The bar 950 is fast to an eccentrically mounted strap 953 on the constantly rotating shaft 572 and is guided for vertical reciprocation in a slot 954 formed in a pin 956 rotatably mounted in the bracket 888. Accordingly, as the finger 928 is moved into position beneath the constantly reciprocating bar 950 the bell crank lever 932 and the arm 884 are swung in a clockwise direction (Fig. 17) to move the rod 882 to the left to tension the spring 928, the spring 944 acting to swing the bell crank lever 892 into the position again to engage the roll 890 and to hold the parts in their initial positions with the spring 928 under tension. It will be understood that as the arm 884 is thus swung in a clockwise direction the spring-pressed plunger 926 acts to swing the finger 928 out from under the lower end of the reciprocating bar 950. An arm 958 pivotally connected at 960 to the bracket 888 and having a pin-and-slot connection 962 with the bar 932 acts to lift the left-hand end portion of the bar 902 out of engagement with the pin 898 in the arm 896 of the bell crank lever 892 in the continued movement of the bar 902 to the right (Fig. 18) after the bell crank lever 892 has been swung in the direction to release the arm 884 to the action of the spring 928, thus releasing the bell crank lever to the action of the spring 944 for return movement into position again to engage the roll 890 in the reverse swinging movement of the arm 884 to tension the spring 928. A spring 964 connected at one end to the arm 904 (Fig. 6) and at the other end to a hook 966 threaded in a block 968 pivotally to the connected to the bracket 888 acts to move the bar 902 reversely, the arm 958 lowering the left hand end portion of the bar into position again to engage the pin 898 as the bar 902 is thus moved.

From the above description it will be evident that the time in each swinging movement of the shoe supporting jack when the leveling roll begins its tipping movement laterally of the shoe is controlled by the device 633 through the previously described mechanism for imparting upward movement to the arms 828, 830 and that the direction of tipping movement of the leveling roll is controlled by the device 802 which, as more particularly hereinafter explained, acts through the bars 822, 872 to determine which of the arms 828, 830 is in operative relation to the roll 826 carried by the lever 804 and, accordingly, which of the opposite acting friction clutches is to be connected to the shaft 482 in response to the upward movement of the arms 828, 830.

For determining the extent of tipping movement imparted to the leveling roll in either direction laterally of the shoe there is provided mechanism, which will now be described, also controlled by the device 802. Loosely mounted on a shouldered stud 970 in the frame 56 of the machine are two arms 972, 974 (Fig. 9). Springs 976, one of which is shown in Fig. 9, tend to swing the arms 972, 974 in the direction to hold the lower end portions of the arms in engagement with a roll 978 carried by a laterally extending arm 980 on the lever 804. The arm 972 has a hook-shaped lower end portion and formed in the bottom face of the arm 974 is a recess 982. Loosely mounted on the stud 970 (Fig. 9) is a U-shaped lever 984 which straddles the arms 972, 974 and has pivotally connected to it an adjustable link 986 which is pivotally connected at its opposite end to the upwardly extending

arm of a lever 988 pivotally connected at 990 to a bracket 853 secured to the frame 56 by screws 855 (Fig. 7). Formed on the U-shaped lever 984 is a laterally extending rib 992 and on each arm 972, 974 a projection 994 which is arranged by engagement with the rib 992 to limit clockwise swinging movement of each arm (Fig. 9) under the action of its spring 976 when the lever 804 is swung in either a clockwise or a counterclockwise direction by one or the other of the arms 828, 830 to connect one or the other of the oppositely acting friction clutches to the shaft 482. The arrangement is such that when the lever 804 is swung in a clockwise direction to connect one of the friction clutches to the shaft 482, it is locked against reverse swinging movement with that clutch connected to the shaft, by the engagement of the hook-shaped lower end of the arm 972 with the roll 978 carried by the lever 804 and when the lever 804 is swung in a counterclockwise direction to connect the other friction clutch to the shaft 482 it is locked against reverse swinging movement by the arm 974, the roll 978 then engaging the arm 974 in the recess 982 formed in the end face of the arm. It will be understood that with one or the other of the oppositely acting friction clutches connected to the shaft 482 a continuous tipping movement in one direction or the other laterally of the shoe will be imparted to the leveling roll and that by unlocking the lever 804 and releasing it and the lever 806, rockshaft 595, lever 796, and sleeve 794 to the action of the springs 816 these parts will be moved to a centralized position, thus causing the friction clutch that was connected to the shaft 482 to be disconnected therefrom to stop the tipping movement of the leveling roll. It will be understood also that because of the previously described connections 40 between the shaft 482 and the leveling roll 58, including the worm 480 and the worm wheel 478, the leveling roll will be held in any inclined position into which it has been moved for operation upon any portion of the shoe bottom.

The connections between the device 802 and the lever 988 for swinging the lever in the direction to impart counterclockwise swinging movement to the U-shaped lever 984 and the arms 50 972, 974 to unlock the lever 804 comprise a pair of downwardly extending arms 996 (Figs. 7 and 10) on the lever 988, which arms engage a pair of laterally extending arms 998 on a lever 1000 fastened to a short vertical shaft 1002 supported in bearings in the bracket 852 (Fig. 10). Fas-55 tened to the shaft 1002 is a lever 1004 and pivotally connected to this lever for swinging move-56 ment about a horizontal axis is an arm 1006 that extends inwardly into position to be engaged by the controlling device, as more particularly hereinafter described, and to be swung in a horizontal plane, either rearwardly or forwardly, to impart turning movement to the vertical shaft 1002. The lever 1004 has a pair of later-60 ally extending arms 1008 and extending between one of these arms and the pivoted arm 1006 is a spring 1010 which tends to hold the arm 1006 with a projection thereon in engagement with the arm 1008. It will be evident that as the shaft 1002 is thus turned in either direction the lever 988 will be swung in a counterclockwise direction (Fig. 7) and through the link 986 and lever 984 (Fig. 9) will swing the arms 972 and 65 974 in the direction to cause one of them to un-70 75

lock the lever 804 and to release it to the action of the springs 816.

The device 802 for determining the direction and extent of tipping movement of the leveling roll 50 is fitted to slide in a bore 1011 in the bracket 852 and along a shaft 1012 the rear end portion of which is supported in a bearing in the bracket 158, a set screw 1014 being provided for holding the shaft against endwise movement and also against turning movement (Fig. 14). The device 802 comprises a bushing 1016 (Fig. 30) slidably mounted on the shaft 1012 and provided with an external flange 1018. Surrounding the bushing 1016 between the inner face 1020 of the flange 1018 and the end face 1022 of a sleeve 1024, also slidably mounted on the shaft 1012, is a hollow cylindrical member 1026 provided with inwardly extending flanges 1028, 1030 at its opposite ends that are bored to provide a drive fit for reduced portions of the flange 1018 and the bushing 1016. The member 1026 at its left-hand end (Fig. 30) is provided with an annular groove 1032 to receive a circular ring 1034 that is held in the groove by the flange 1018 on the bushing 1016 and is fitted to slide in the bore 1011 in the bracket 852. Secured to the sleeve 1024 by a pin 1036 is a tongue 1038 that extends forwardly in a groove 1040 in the sleeve 1024 and in a groove 1042 in the bushing 1016. The tongue has formed on its forward end a head 1044 that acts by engagement with the end face 1046 of the bushing 1016 to hold the parts in assembled relation on the shaft 1012. Formed in the shaft 1012 is a groove 1048 into which the forward end of the tongue may be depressed by the operator to permit removal of the bushing 1016 and the member 1026.

The flanges 1028, 1030 of the member 1026 are bored to receive spaced rotatable shafts, herein illustrated as eleven in number and designated by the reference numerals: 1050, 1052, 1054, 1056, 1058, 1060, 1062, 1064, 1066, 1068 and 1070 (Fig. 31). Each shaft has formed thereon a collar 1072 which is seated in a counterbore in the flange 1028 and engages the inner face 1020 of the flange 1018 to prevent endwise movement of the shaft when the parts are in assembled relation, the left-hand end portion of each shaft extending forwardly through a bore in the flange 1018. Threaded on each shaft is a block 1074 provided with a projection or finger 1076 that extends outwardly through a slot 1075 in the member 1026. To prevent turning movement of the device 802 relatively to the shaft 1012, the ring 1034 is recessed at 1078 (Fig. 31) slidably to engage a shaft 1080 which is supported at one end in the bracket 852 and at its opposite rear end in the bracket 158. In the illustrated construction the shafts 1050, 1052, 1054 and 1056 are geared together by means of pinions 1082 pinned to the rear end portions of the shafts, the shaft 1056 at its forward end being formed to receive a socket wrench so that it may be rotated by the operator and through the gears 1082 rotate the shafts 1050, 1052 and 1054. It will be understood that as these shafts are rotated the blocks 1074 threaded on the shafts are moved lengthwise of the shafts, since they are held against turning movement with the shafts by engagement of their respective fingers 1076 with the member 1026 in the slots 1075.

As previously pointed out, the bars 862, 872 for controlling the arms 828, 830 are pivotally connected at 864 to the bracket 852 and are held

initially by springs 874 in engagement with the shoulder 878 on the bracket 852 with both arms 828, 830 out of operative relation to the roll 826 carried by the downwardly extending arm 820 of the lever 804. By reference to Fig. 7 it will be seen that the bars 862, 872 extend lengthwise of the device 802 and are spaced apart equidistant from the vertical axis of the shaft 1002 about which the arm 1006 is mounted for swinging movement. By reference to Fig. 8 it will be seen that the pivoted arm 1006 straddles the hub of the lever 1004 and extends inwardly in the vertical plane of the axis of the shaft 1002. When the machine is initially at rest the block 1074 on the shaft 1050 will have been adjusted lengthwise of the shaft into position to engage one or the other of the bars 862, 872 and to hold the bar outwardly with its associated arm 828, 830 in operative relation to the roll 826 carried by the lever 804, thus determining the direction of tipping movement to be imparted to the leveling roll in the first rearward swinging movement of the shoe supporting jack. It will be understood that the time in the first rearward movement of the jack, when the leveling roll is tipped, is controlled by the device 633 by the engagement of one of the fingers 918 of that device with the pin 916 to cause the bar 902 to be moved to the right (Fig. 6) to unlock the arm 884 and to release it and the rod 882 to the action of the spring 920 to impart upward movement to the arms 828, 830. In the illustrated construction the downwardly extending arm 430 of the lever 432 (Fig. 22) carries a roll 1084 that extends into an annular groove 1086 in the sleeve 1024. Accordingly, the device 802 is moved along the shaft 1012 in response to the tipping of the leveling roll either in a rearward or forward direction, depending upon the direction of tipping movement of the leveling roll. The extent of tipping movement imparted to the leveling roll will, of course, depend upon how far the device 802 moves relatively to the shaft 1012 to bring the finger 1076 of the block 1074 on the shaft 1050 into engagement with the arm 1006 and to cause the finger to swing the arm in one direction or the other to impart counterclockwise movement to the lever 928 (Fig. 7) to unlock the lever 804. By rotation of the shaft 1056 the finger 1076 may be adjusted lengthwise of the shaft 1050 into such relation to the arm 1006 as to cause the tipping of the leveling roll to terminate after the roll has received a tipping movement of predetermined extent.

For indexing the device 802 to move the fingers 1076 successively into position to act on one or the other of the bars 862, 872 and on the finger 1006, there is provided mechanism which is generally similar to that previously described for indexing the controlling device 633. As shown particularly in Figs. 30 and 31 there is loosely mounted on the sleeve 1024 a two-part bracket 1088 carrying a shouldered stud 1090 on which is rotatably mounted a gear 1092 the teeth of which mesh with the teeth of a gear 1094 formed integral with the sleeve 1024. The gear 1092 meshes with a gear 1096 rotatably mounted on a shouldered stud 1098 in the sleeve 1024 and with a relatively long gear 1100 fast to a shaft 1102 supported partly by a bearing in the bracket 852 and partly by a bearing in the bracket 158 of the machine (Fig. 9). For holding the bracket 1088 against turning movement about the axis of the shaft 1012 in response to rotation of the gear

1100, while permitting movement of the device 802 length-wise of the shaft 1012 in response to tipping of the leveling roll, there is formed on the bracket 1028 a downwardly extending forked arm 1104 that straddles the shaft 1080 and engages flat surfaces 1106 formed on the opposite sides of the shaft.

The gear 1108 meshes with a gear 1109 fast on a shaft 1110 (Fig. 7) which is supported partly by a bearing in the frame 56 and partly by a bearing in a bracket 1112 secured by screws 1114 (Fig. 10) to the bracket 852. Loosely mounted on the shaft 1110 is a grooved pulley 1116 (Fig. 9) which is constantly driven by means of the belt 734. Formed integral with the pulley 1116 is a disk 1118 similar to the disk 738 of the pulley 732 on the shaft 376 (Fig. 24), the disk 1118 having its edge face also provided with a plurality of recesses and lands. Yieldingly engaging the edge face of the disk 1118 are rolls 1120 carried by levers 1122 that are pivotally connected to a second disk 1124 fast to the shaft 1110, spring-pressed plungers (not shown) being provided in the hub of the disk 1124 similar to the plungers 750 in the hub of the disk 744 on the shaft 376. Keyed to the shaft 1110 are two ratchet wheels 1126 and 1128 (Figs. 7 and 10) and pivotally connected to the bracket 852 are two pawls 1130 and 1132 which are arranged respectively to cooperate with the ratchet wheels 1126 and 1128 to hold the shaft 1110 against rotation similarly to the pawls 760, 762 of the indexing mechanism for the device 633. The pawl 1132 has a tail portion which is connected by a link 1134 (Fig. 10) to one end of a lever 1136 connected at its opposite end by a link 1138 to the pawl 1130. Intermediate between its ends the lever 1136 is pivotally connected to an adjustable rod 1140 that extends upwardly through spaced bearings on the bracket 852 and has at its upper end a head 1142 provided with an annular groove 1144 into which extends a pin 1146 carried by one arm of a forked lever 1148 which is fulcrumed at 1150 to the bracket 852 (Figs. 7 and 10a). Between the arms of the forked lever 1148 there is pivotally connected to the arms a lever 1152 provided with a forwardly extending arm 1154 to which there is pivotally connected a block 1156 slidably mounted on a rod 1158 fulcrumed at 1160 to the bracket 852. Surrounding the rod 1158 at opposite sides of the block 1156 are springs 1162 engaging the top and bottom faces of the block and bearing at their opposite ends against nut and lock nuts 1164 threaded on the rod 1158. The lever 1152 has a rearwardly extending curved arm 1166 (Fig. 7) to which there is pivotally connected a block 1168 through which extends an adjustable rod 1170 the forward end of which bears against an inclined surface 1172 formed on the hub of the lever 1148. At its opposite end the rod 1170 is pivotally connected to an arm 1174 on the lever 988. A spring-pressed plunger 1176 in the bracket 852 tends to swing the lever 988 in a clockwise direction (Fig. 7) and to hold it with its downwardly extending arms 996 in engagement with the laterally extending arms 998 on the lever 1000.

Initially the rod 1170 engages the inclined surface 1172 on the lever 1148 in a location below the pivotal connection 1150 of the lever to the bracket 852. Accordingly, as the lever 988 is swung in a counterclockwise direction (Fig. 7) by the action of one of the fingers 1076 of the device 802 on the arm 1006 to stop the tipping movement of the leveling roll, the rod 1170 acts to impart clockwise

swinging movement to the lever 1148. As the lever 1148 is thus swung it acts to move the rod 1140 upwardly. Upward movement of the rod 1140 causes the pawl 1132 to be moved downwardly into engagement with the ratchet wheel 1128 and the pawl 1130 to be moved upwardly out of engagement with one of the ratchet teeth on the wheel 1126. Since the ratchet wheels 1126 and 1128, as shown, are assembled with their teeth in staggered relation, the shaft 1110 will accordingly be rotated in a clockwise direction (Fig. 10) by the disk 1118 until one of the teeth of the ratchet wheel 1128 engages the end of the pawl 1132. By reference to Fig. 7 it will be seen that as the lever 1148 is swung in a clockwise direction it acts to compress the spring 1162 that surrounds the upper end portion of the rod 1158 above the block 1156. The construction is such that as the lever 988 is released to the action of the spring-pressed plunger 1176 for clockwise swinging movement the compressed spring 1162 acts to swing the lever 1152 about its pivotal connection to the lever 1148 in a counterclockwise direction, thus raising the guide block 1168 and positioning the rod 1170 for engagement with the inclined surface 1172 on the lever 1148 in a location above its pivotal connection 1150 to the bracket 852. Thereafter, as the lever 988 is again swung counterclockwise, the rod 1140 is lowered to move the pawl 1130 downwardly into position to engage one of the ratchet teeth on the wheel 1126 and the pawl 1132 is raised to release the shaft 1110 for one indexing movement, the spring 1162 surrounding the rod 1158 below the block 1156 acting to swing the lever 1152 clockwise to lower the guide block 1168 with the rod 1170 again in position to engage the inclined face 1172 on the lever 1148 in a location below its pivotal connection to the bracket 852. The rod 1140 is thus alternately raised and lowered, in response to counterclockwise swinging movement of the lever 988 to stop tipping of the leveling roll, to operate the pawls 1130 and 1132 to permit intermittent rotation of the shaft 1110 which acts through the above-described gearing to rotate the device 802 step by step about the axis of the shaft 1012, thus moving the fingers 1076 successively into position to act on one or the other of the bars 862, 872 and on the arm 1006.

The shafts 1050, 1052, 1054 and 1056 of the device 802 (Figs. 30 and 31) are so threaded that as the shaft 1056 is turned by the operator, as above described, to impart rotation to all of the shafts to adjust the block 1074 of the shaft 1050 with its finger 1076 in the desired relation to the arm 1006, the blocks 1074 on the shafts 1052, 1054 and 1056 will be adjusted with their fingers 1076 in such relation to the arm 1006 as to cause the leveling roll to receive successive tipping movements in the desired direction and to the desired extent in the forward and rearward movements of the jack as the leveling roll is operating on the outside shank portion of the shoe bottom in accordance with the cycle of relative movements of the jack and roll in directions lengthwise of the shoe indicated diagrammatically in Fig. 29 by the line 1180. With reference to the line 1180, the time in the first rearward swinging movement of the jack and the times in the forward and rearward swinging movements of the jack when the roll is operating in the shank are indicated by the reference letters T¹, T², T³, and T⁴, the arrows indicating the directions of such tipping movements. It will be understood that the direction and extent of such tipping movements of the roll

are controlled by the fingers 1076 of the blocks 1074 on the shafts 1053, 1052, 1054 and 1056. As the roll is returned to the forepart it is tipped at T⁶ in the direction indicated by the arrow and to the extent determined by the adjusted position of the finger 1076 of the block 1074 on the shaft 1053. The shaft 1058 is not geared to any one of the other shafts and may be rotated by the operator independently to adjust its associated block 1074. Thereafter, the leveling roll traverses the outer edge portion of the forepart rearwardly to the junction of the forepart and shank without any further tipping movement being imparted to it, after which the roll returns to the toe end along the outer edge portion of the forepart and it is during this movement of the jack that the roll receives a continuous tipping movement at a relatively slow rate to cause it properly to level this portion of the forepart. It will be understood that this slow continuous tipping movement of the roll is not controlled by the device 802 but is effected through the mechanism previously described comprising the arm 466 which is released for downward movement into position to cause the pin 499 in the arm 488 of the lever 484 to engage the hook-shaped end 483 of the arm 466 and to exert a forward pull upon the arm 466 in response to the forward swinging movement of the jack.

As the leveling roll reaches the toe end of the shoe it is tipped at T⁶ (Fig. 29), in the direction indicated by the arrow, across the toe end to assist in leveling that portion of the sole, this tipping movement continuing until the roll is inclined in the opposite direction for operation upon the opposite side of the forepart. Since this tipping movement of the leveling roll may be of considerable extent the illustrated machine is provided with mechanism for locking the shoe supporting jack against swinging movement supporting jack against swinging movement in lengthwise of the shoe with the leveling roll in that location on the shoe bottom and for releasing the jack for such swinging movement only when the tipping movement of the roll has been completed. This mechanism comprises a downwardly extending arm 1182 formed integral with the previously-mentioned upwardly extending arm 600 which is fast to the bushing 594 that surrounds the shaft 595 (Figs. 4 and 15). The arm 1182 carries a roll 1184 that extends into a substantially V-shaped recess 1186 (Fig. 16) formed in one arm of a lever 1188 pivotally connected at 1190 to the bracket 158. The recess 1186 is large enough to permit the arm 1182 to swing in one direction or the other, as the bushing 594 is turned in one direction or the other about the shaft 595 to cause one or the other of the friction clutches 518, 520 to be connected to the shaft 156, without the roll 1184 engaging either of the inclined surfaces 1192 of the recess 1186. When it is desired, however, to lock the jack against swinging movement the lever 1188 is swung in a clockwise direction (Fig. 16) and is engaged with the roll 1184 in the recess 1186 the arms 1182 and 600 are moved to a substantially vertical position and through the bushing 594 and the lever 592 the sleeve 590 is moved to a central position with both friction clutches 518, 520 disconnected from the shaft 156. For locking the lever 1188 against reverse swinging movement with both friction clutches 518, 520 disconnected from the shaft 156 there is pivotally connected to the bracket 158 a lever 1194 (Fig. 16) provided with a downwardly extending arm 1196 having formed in its end face a recess 1198 for

engagement with a roll 1200 carried by the rearwardly extending arm 1202 of the lever 1188. A spring 1204 extending between the lever 1188 and the lever 1194 tends to swing the lever 1194 in a clockwise direction (Fig. 16) and to hold it with the arm 1196 engaging the roll 1200 in a recess 1206 in the end face of the arm. As the lever 1188 is swung in a clockwise direction (Fig. 16), the spring 1204 acts to swing the lever 1194 in the same direction until the arm 1196 engages the roll 1200 in the recess 1198, thus locking the lever 1188 against reverse swinging movement.

For imparting clockwise swinging movement to the lever 1188 (Fig. 16) there is provided a pin 1208 (Fig. 4) which is reciprocated each time in the operation of the machine when the arms 828, 830 are moved upwardly to connect one or the other of the oppositely acting friction clutches to the shaft 482 to start the tipping movement of the leveling roll 50. For reciprocating the pin 1208 there is fast to the shaft 840 (Fig. 11) a downwardly extending arm 1210 to which there is pivotally connected an adjustable rod 1212 pivotally connected at its opposite end to a downwardly extending arm 1214 (Fig. 6) fast to a shaft 1216 mounted in the bracket 158. Fast to the shaft 1216 is a second laterally extending arm 1218 (Figs. 4 and 6) having pivotally connected to it a link 1220 in which the pin 1208 is threaded, a lock nut 1222 being provided for holding the rod against turning movement in the link 1220. The pin 1208 extends upwardly through a block 1224 pivotally connected to an arm 1226 pinned to the rear end portion of a shaft 1228 supported in bearings on the bracket 158. Fast to the shaft 1228 is an arm 1230 and extending laterally of the machine and supported in bearings on the bracket 158 is a rod 1232 one end of which engages the arm 1230 and the other end of which engages the upper end of an arm 1234 fast to a forwardly extending shaft 1236 supported partly by a bearing in the bracket 158 and partly by a bearing in the bracket 1112. Secured to the forward end of the shaft 1236 is a cam lever 1238 (Figs. 7 and 10) carrying a cam roll 1240 engaging the edge face of a cam member 1242 keyed to the shaft 1110. Surrounding the shaft 1228 (Fig. 4) between the bracket 158 and a collar 1244 fast to the shaft is a torsion spring 1246 that tends to rotate the shaft 1228 in the direction to hold the arm 1230 in engagement with the rod 1232 and through the rod 1232, arm 1234 and shaft 1236 to hold the roll 1240 against the edge face of the cam member 1242.

It will be understood that each time in the cycle of the machine when the arms 828, 830 are moved upwardly by the action of the spring 920 on the rod 882 to connect one or the other of the oppositely acting friction clutches to the shaft 482 to start the tipping of the leveling roll, the arm 1210 will be swung in a counterclockwise direction (Fig. 11) and through the rod 1212 and arms 1214 and 1218 upward movement will be imparted to the pin 1208. Formed on the lever 1188 is a boss 1248 (Fig. 16) with which the pin 1208 contacts in its upward movement when it is desired to impart clockwise swinging movement to the lever 1188 to lock the jack against swinging movement. The pin 1208 is held initially by the arm 1226 in an inclined position out from under the boss 1248 and is moved into a substantially vertical position beneath the boss at the proper time in the cycle by a rise 1250 in the edge face of the cam member 1242 (Fig. 10). As previously pointed out when the leveling roll 50 reaches

the toe end of the shoe after having traversed the outer edge portion of the forepart it is tipped at T⁶ (Fig. 29). The direction and extent of this tipping movement of the roll is determined by the finger 1076 of the block 1074 on the shaft 1069. As the device 802 is indexed to bring the finger 1076 of the block 1074 on the shaft 1069 into operative relation to the arm 1006, the finger acts by engagement with one or the other of the bars 862, 872 to determine the direction of tipping movement of the roll. As the device 802 is thus indexed the rise 1250 on the cam member 1242 acts to swing the lever 1238 in the direction to cause the pin 1288 to be moved into position beneath the boss 1248 on the lever 1188. Thereafter as the arms 822, 830 are moved upwardly to start the tipping movement of the leveling roll the pin 1208 is moved upwardly to swing the lever 1188 in a clockwise direction (Fig. 16) and thus to prevent connection of either one of the oppositely acting friction clutches 518, 520 to the shaft 156. As the leveling roll is thus tipped the device 802 is moved along the shaft 1012 until the finger 1076 engages and swings the arm 1006 far enough to effect the unlocking of the lever 804. When this occurs one of the springs 816 acts to swing the levers 804, 806 and to turn the shaft 595 in a clockwise direction (Fig. 9) to cause the shaft 482 to be disconnected from one or the other of its associated friction clutches to stop the tipping movement of the leveling roll. Fast on the shaft 595 (Fig. 16) is a laterally extending arm 1252 carrying a roll 1254 and formed on the lever 1194 is an arm 1256 that lies in the path of movement of the roll 1254. As the shaft 595 is turned in a clockwise direction, as viewed in Fig. 16, the roll 1254 acts by engagement with the arm 1256 to swing the lever 1194 in a direction to release the lever 1188 to the action of the spring 1204 for counterclockwise swinging movement. It will be understood that as the roll reaches the toe end of the shoe in the location indicated by the reference letter T⁶ (Fig. 29), the rod 610 is moved forwardly to cause the clutch 518 to be connected to the shaft 156 to impart rearward swinging movement to the jack and that it is at this time in the operation of the machine when the lever 1188 is swung upwardly in a clockwise direction (Fig. 16) to prevent the friction clutch 518 from being connected to the shaft 156, the spring 614 being compressed in response to the swinging of the arms 1182 and 609 by engagement of the arm 1188 with the roll 1184. As the lever 1188 is swung reversely by the spring 1204 to release the arms 1182 and 609, the spring 614 swings the arms 600 and 1182 and rotates the bushing 594 in the direction to connect the friction clutch 518 to the shaft 156 to start the rearward swinging movement of the jack after the tipping movement of the leveling roll when in that location on the sole has been completed.

In the next rearward swinging movement of the shoe supporting jack to cause the leveling roll to transverse the bottom of the shoe from the toe and rearwardly to the heel end portion of the shoe, the leveling roll is tipped at T⁷ (Fig. 29), the direction and extent of this tipping movement of the roll being controlled by the finger 1076 of the block 1074 on the shaft 1062. The shafts 1069 and 1062 are geared together and the adjusted positions of the blocks 1074 on the shafts are controlled by rotation of the shaft 1060 which, as shown in Fig. 31, has its forward end portion formed to receive a socket wrench. 70 75

As the jack is swung forwardly and rearwardly while the roll is operating on the inside shank portion of the shoe, the roll is tipped at T⁸, T⁹, and T¹⁰, the direction and extent of these tipping movements of the roll being controlled by the fingers 1076 of the blocks 1074 on the shafts 1064, 1066 and 1068. These three shafts are also geared together independently of the other shafts and one of them, the shaft 1068, has its forward end formed to receive a socket wrench so that the three shafts may be rotated to adjust the positions of their associated blocks 1074. Thereafter the leveling roll is again tipped at T¹¹ for operation upon the inner edge portion of the ball and forepart of the shoe bottom after which it is returned to the toe end and at T¹² is tipped to return it to a horizontal or straightened position before traversing the forepart rearwardly substantially to the junction of the forepart and shank and then forwardly to the toe end and leaving the shoe. The direction and extent of the tipping of the roll at T¹¹ is controlled by the finger 1076 of the block 1074 on the shaft 1070 which is not geared to any one of the other shafts and is independently rotatable to vary the position of its associated block 1074. The tipping of the leveling roll at T¹² to return it to a horizontal position is controlled by a pin 1258 in the member 1026, this pin acting by engagement with the appropriate bar 862, 872 to cause the roll to be tipped in the direction to straighten the roll and by engagement with the arm 1006 to stop the tipping of the roll when it is in a straightened position. 35 40 45 50 55 60 65 70 75

Each bar 862, 872 is provided with a downwardly extending arm 1260 (Figs. 8 and 10) and held yieldingly in engagement with the lower end of each arm 1260 by a spring 1262 is a latch 1264 pivoted at 1266 to the bracket 852. Each latch is stepped or notched for engagement with the lower end of its associated arm 1260 so that as each bar 862, 872 is swung in a counterclockwise direction (Fig. 10) by engagement of one of the fingers 1076 therewith as the device 802 is indexed, the bar is held in the position into which it has been moved by the finger against the action of its associated spring 874 while the device 802 is moved lengthwise of the shaft 1012 in response to the tipping of the leveling roll. For operating each latch 1264 to release its associated bar 862, 872, there is pivotally connected to the bracket 852 at 1267 a lever 1268 provided with a pair of upwardly extending arms 1270 that engage the laterally extending arms 1008 on the lever 1004. The lever 1268 has a pair of downwardly extending arms 1272 into engagement with one of which one of the latches 1264 is moved as it is swung by its spring 1262 into position to hold its associated bar 862, 872 in the position into which the bar has been moved by one of the fingers 1076. As the finger 1076 acts on the arm 1006 to turn the shaft 1002 in either direction, one of the oppositely extending arms 1008 of the lever 1004 will act by engagement with one of the arms 1270 to swing the lever 1268 in a counterclockwise direction (Fig. 10). As the lever 1268 is thus swung, one or the other of the latches 1264 will be operated to release its associated arm 1260, thus permitting the spring 874 to move one or the other of the bars 862, 872 again into position to engage the shoulder 878 on the bracket 852. 70 75

Pinned to the forward end of the shaft 864 (Figs. 7, 10 and 31) is a guard 1274 held normally in position to prevent removal of the device 802 from the machine. Fast to the opposite end po-

sition of the shaft 864 (Fig. 8) is a collar 1276 provided with a recess 1278 to receive a pin 1280 projecting from the bracket 852. A spring 1282 connected at one end to a pin 1284 in the collar 1276 and at the other end to a pin 1286 in the bracket 852 tends to rotate the shaft 864 in the direction to hold the collar 1276 in engagement with the pin 1280 at one end of the recess 1278 when the guard is in the position shown in Fig. 10 and to rotate the shaft 864 in the opposite direction to hold the collar in engagement with the pin 1280 at the opposite end of the recess 1278 when the guard has been moved to an inoperative position which may be effected by means of a hand lever 1288 formed integral with the guard 1274. Also pinned to the intermediate portion of the shaft 864 is a sleeve 1290 having formed thereon a projection 1292 (Figs. 8 and 10) and laterally extending arms 1294. As the shaft 864 is rotated by the hand lever 1288 in the direction to move the guard into an inoperative position, the arm 1006 is raised to an out-of-the-way position by the action of the projection 1292 on a pin 1296 slidably movable in the bar 872. As the shaft 864 is thus rotated in the direction to move the guard 1274 to an inoperative position the latches 1264 are swung by engagement of the arms 1294 with pins 1298 projecting from the latches, the pins 1298 engaging the arms 1260 and swinging the bars 862, 872 into an out-of-the-way position. It will be understood that as the hand lever 1288 is swung reversely to move the guard 1274 again into position to prevent removal of the device 802, the springs 874 will move the bars 862, 872 into engagement with the shoulder 878 on the bracket 852 in position to be engaged by the fingers 1076 of the blocks 1074 and the arm 1006 will be swung downwardly into operative relation to the fingers 1076.

In the illustrated machine, when each shaft 156, 482 is disconnected from one or the other of its oppositely acting friction clutches, the motion of each shaft is immediately arrested by the action of a friction brake to stop the swinging movement of the shoe supporting jack or the tipping movement of the leveling roll. Since the friction brakes for the shafts 156, 482 are identical in construction a description of one will suffice for both. Keyed to the rear end of the shaft 156 (Fig. 16) is a flange 1300 the peripheral edge face 1302 of which is inclined relatively to the axis of the shaft. Associated with the flange 1300 is a second flange 1304, the hub of which is bored slidably to engage a cylindrical surface 1306 on the flange 1300. Carried by the flange 1300 are pins 1308 that extend through openings in the flange 1304 and surrounding each pin 1308 is a spring 1310 that bears at one end against a shoulder 1312 on the flange 1304 and at the other end against a washer 1314 supported by a cotter pin 1316 carried by the pin 1308. Each pin 1308 is provided with a head 1317 that engages the side face 1318 of the flange 1300. The peripheral edge face 1320 of the flange 1304 is inclined relatively to the axis of the shaft 156 in a direction opposite to the direction of inclination of the edge face 1302 of the flange 1300 and surrounding both these flanges is a brake shoe in the form of a ring 1322 the inner face of which is inclined in opposite directions for engagement with the inclined edge faces 1302 and 1320 of the flanges 1300 and 1304. It will be understood that the springs 1310 tend to move the flange 1304 toward the flange 1300 and that the flanges are held in spaced relation against

the resistance of the springs 1310 by the brake shoe 1322. A shouldered stud 1324 (Fig. 16) is provided for preventing relative rotation of the flanges 1300, 1304. Formed on the brake shoe 1322 are a plurality of spaced projections or teeth 1326 and pivotally connected to the bracket 158 are a pair of oppositely extending arms 1328 (Fig. 15) each of which carries a pin 1330 that extends into an elongated slot 1332 formed in the upwardly extending arm 1334 of a lever 1336 which is pivotally connected to the rearwardly extending arm 1338 of a lever 1340 pivoted at 1342 to the bracket 158 (Fig. 16). The arms 1328 are held with the pins 1330 engaging the arms 1334 at the upper ends of the slots 1332 by springs 1344 seated in recesses in the lever 1336. The lever 1340 has a forwardly extending arm to which there is pivotally connected a toggle link 1346 pivotally connected at its upper end to a forwardly extending link 1348 and to the other link 1350 of a toggle which is pivotally connected at 1352 to the bracket 158. In the right-hand half of the machine, the link 1348 (Figs. 4 and 16) at its forward end is pivotally connected to the lower end of the previously mentioned arm 1182. The construction is such that as the arms 600 and 1182 are swung in a counterclockwise direction (Figs. 4 and 16) to cause one of the oppositely acting friction clutches 518, 520 to be disconnected from the shaft 156 and the other clutch to be connected thereto, the toggle links 1346, 1350 are first swung into parallel relation to each other as one of the friction clutches is disconnected from the shaft 156 after which they are swung into non-parallel relation as the oppositely acting clutch is connected to the shaft. Straightening of the toggle 1346, 1350 will cause the lever 1340 to be swung in the direction to raise the lever 1336 thereby imparting upward swinging movement to the arms 1328 to cause one or the other of them by engagement with one of the teeth 1326 to stop rotation of the brake shoe 1322 with the flanges 1300 and 1304, and movement of the toggle links into a non-parallel relation, will act to swing the lever 1340 reversely to lower the arms 1328 out of operative relation to the teeth 1326 to permit rotation of the brake shoe with the flanges. It will be understood that by reason of the frictional engagement of the brake shoe with the flanges 1300 and 1304 rotation of the shaft 156 is immediately stopped when the rotation of the brake shoe is stopped, the construction being such that as each of the oppositely acting clutches 518, 520 is disconnected from the shaft 156 the brake is applied to stop further rotation of the shaft, after which the brake is released, to permit rotation of the shaft in the opposite direction, as the other friction clutch is connected to the shaft.

In the left-hand half of the machine the link 1348 at its forward end is pivotally connected to the lower end of the downwardly extending arm 822 of the forked lever 804 which is loosely mounted on the left-hand end of the shaft 595. As previously pointed out, when both of the oppositely acting friction clutches are disconnected from the shaft 482 the springs 816 (Fig. 9) tend to hold the lever 804 in a central position. When the lever 804 is thus held by the springs the toggle links 1346 and 1350 are in parallel relation to each other. The friction brake is accordingly applied to the shaft 482, since with the toggle links in parallel relation the arms 1328 are upheld in position to engage one of the teeth 1326

on the brake shoe 1322 (Fig. 11). As the lever 804 is swung in one direction or the other by one or the other of the upwardly moving arms 828, 830, the toggle links 1346, 1350 are moved into non-parallel relation to release the friction clutch, after which, as the lever 804 is returned to its normal central position, the toggle links are again swung into a straightened condition to cause the friction brake again to be applied to the shaft 482.

The illustrated machine is further provided with means enabling the operator at will to stop the swinging movement of the shoe supporting jack at any point in the operation of the leveling roll on the bottom of the shoe. This means comprises a treadle 1354 (Fig. 3) journaled at 632 to the frame 56 and provided with a forwardly extending arm 1356 which is connected by a link 1358 to one arm of a bell crank lever 1360 pivotally connected to the frame 56 by the pin 516. The bell crank lever 1360 has an upwardly extending arm 1364 to which there is connected a rearwardly extending adjustable rod 1366 pivotally connected at its rear end to the downwardly extending arm of a bell crank lever 1368 loosely mounted on the shaft 1190 (Fig. 16). The bell crank lever 1368 has a forwardly extending arm 1370 which is arranged to engage a pin 1372 projecting from the lever 1188 as the bell crank lever 1368 is swung in a clockwise direction (Fig. 16) in response to depression of the treadle 1354. It will be evident that clockwise swinging movement will be imparted to the lever 1188 in response to further depression of the treadle and as the lever 1188 is thus swung one or the other of the inclined surfaces 1192 on the lever 1188 will act by engagement with the roll 1184 to swing the arms 1182 and 608 into a central, substantially vertical, position, thus causing both friction clutches 518, 520 to be disconnected from the shaft 156. It will be understood that as the arm 1182 is thus swung the toggle links 1346 and 1350 will be moved into parallel relation to each other, thus causing the friction brake to be applied to the shaft 156. In order to prevent locking of the parts in the positions just described by engagement of the arm 1196 with the roll 1200 in the recess 1198 in the arm, the bell crank lever 1368 is provided with a rearwardly extending arm 1374 which, as the bell crank lever 1368 is swung in a clockwise direction by depression of the treadle 1354, is moved downwardly into position to be engaged by a pin 1376 carried by the arm 1196, and thus to act as a stop to prevent movement of the arm 1196 into locking relation to the lever 1188. A spring 1378 connected at one end to the treadle 1354 and at the other end to the frame 56 acts to uphold the treadle with the parts in the positions shown in Fig. 16, an adjustable stop illustrated as a screw 1380 carried by a frame 56 being provided for limiting the upward movement of the treadle.

As previously pointed out, the arm 884 and the rod 882 (Fig. 11) are released by mechanism, controlled by the device 693, to the action of the spring 920 each time in the cycle of the machine when it is desired to impart tipping movement to the leveling roll. As the arm 884 and the rod 882 are thus released, the spring 920 acts to move the rod to the right (Fig. 11) and through the connections previously described imparts upward movement to the arms 828, 830 to cause one of them to operate the lever 884 to connect one of the friction clutches to the shaft 428. In order to prevent these parts from being operated too

rapidly under the action of the spring 920, such as might tend to damage them, the illustrated machine is provided with a dash pot for retarding the movements of the parts. This dash pot 5 comprises a cylinder 1382 (Fig. 9) in which there is fitted to slide a piston 1384 connected by means of a link 1386 to an arm 1388 on the lever 830 to which the arms 828, 830 are pivotally connected. The cylinder 1382 has at its upper end 10 a restricted passage 1390 permitting only a slow admission and exhaustion of air to and from the cylinder in response to the reciprocations of the piston 1384.

It will be understood that after a last and shoe 15 has been mounted on each shoe supporting jack, the jack is swung by the operator rearwardly into position to be connected to its associated power-operated arm 148 by means of the spring-operated pin 150 carried by that arm. At the end of 20 the leveling operation each jack is unlocked from its associated arm 148 to permit it to swing outwardly to its initial starting position. For thus disconnecting each jack and its associated arm 148 there is pivotally connected to each arm 148 25 a lever 1392 (Figs. 19 and 20) provided with an upwardly extending arm 1394 carrying at its upper end a pin 1396 that extends upwardly through an elongated slot 1398 in the arm 148 and engages the pin 150 in a recess 1400 formed in the pin (Fig. 19). Each lever 1392 is provided 30 with a downwardly extending arm 1402. Pivotally connected to the previously mentioned arm 212 (Fig. 20) is a forked forwardly extending arm 1404 provided with a wedge-shaped forward end portion 1406. The arm 1404 is connected by 35 means of a link 1408 to the forwardly extending arm 1410 of a bell crank lever 1412 pivotally connected to the previously mentioned arm 208. The bell crank lever 1412 has a second arm 1414 40 carrying a roll 1416 and extending between this arm 1414 and a pin 1418 projecting from a depending portion 1420 on the arm 1404 is a spring 1422 that tends to hold the parts in the positions 45 shown in Fig. 20 with a lug 1424 on the link 1408 in engagement with a lug 1426 on the arm 1410. Secured to the bracket 179 by screws 1428 is a plate 1430 provided with a rearwardly extending tapered portion 1432. It will be understood that 50 as the arm 208 is swung forwardly and rearwardly in the operation of the machine, in response to rotation of the shaft 156 and the worm 157 in opposite directions, swinging movement in the same direction as the arm 208 will be imparted to the shoe supporting jack through the 55 previously described connections between the arm 208 and the jack. Accordingly, as the arm 208 and the jack are swung forwardly far enough to carry the toe end of the shoe out from under the leveling roll 59, the end face of the tapered portion 1432 of the plate 1430 will act by engagement with the roll 1416 to cause the bell crank lever 1412 to be swung relatively to the arm 208 in a clockwise direction, as viewed in Fig. 20. As the bell crank lever 1412 is thus swung it acts 60 through the link 1408 to impart swinging movement to the arm 1404 in the same direction from the position shown in Fig. 19 to the position shown in Fig. 20. As the arm 1404 is thus swung, its wedge-shaped end portion 1406 acts by engagement with the rounded lower end portions 65 of the arms 1402 of the levers 1392 to swing the levers toward each other to withdraw one or both of the pins 150 from engagement with the toe post of the jacks in the recesses 152 formed 70 in the toe posts. As each pin 150 is thus withdrawn

drawn, its associated shoe supporting jack falls forwardly to its initial shoe receiving position.

In the illustrated machine the swinging movement of each shoe supporting jack toward its initial shoe receiving position is retarded by means of a dash pot comprising a cylinder 1434 secured to the frame 56 of the machine by screws 1436 (Figs. 1 and 7). Fitted to slide in each cylinder is a plunger 1438, and formed in the closed end portion of each cylinder is a restricted passage 1440 permitting a slow admission and exhaustion of air to and from the cylinder. The cylinder 1434 is bored to receive a rod 1442 the left-hand end portion of which (Fig. 7) is threaded in the enlarged head portion 1444 of the plunger 1438, a set screw 1446 being provided for holding the rod against movement from adjusted position relatively to the plunger. Surrounding the rod 1442 between the head 1444 of the plunger and a shoulder 1448 in the cylinder is a spring 1450 that tends to move the plunger 1438 to the left, movement of the plunger in that direction being limited by engagement of a nut 1452 threaded on the right-hand end of the rod with the end face 1454 of the cylinder 1434. The toe post 52 of each shoe supporting jack is provided with a depending arm 1456 which, as the jack begins its swinging movement forwardly toward its initial shoe receiving position, engages the head 1444 of the plunger 1438, the plunger being then forced to the right (Fig. 7) by the weight of the parts until the head 1444 of the plunger engages a finished surface 1458 on the cylinder 1434. It will be understood that because of the restricted passage 1440 the air will be exhausted slowly from the cylinder 1434 as the plunger is thus moved. This will act to retard the forward swinging movement of the jack to its initial starting position, thus avoiding any danger of damage to the parts. It will be understood that in the next operation of the machine as the jack is swung rearwardly by the operator to connect it again to its associated arm 148 the spring 1450 will act to return the plunger 1438 to its initial position.

It will be understood also that in the power operation of the machine the number of rearward and forward swinging movements imparted to the shoe supporting jack and the extent of each such swinging movement is controlled by the device 633 which also controls the time in each swinging movement of the jack when the leveling roll 50 begins its tipping movement, and that the direction and extent of each tipping movement of the leveling roll is controlled and determined by the device 802. It will be understood that in operating upon shoes of different styles the machine may be used without the disk 374 so as to cause the pressure of the leveling roll 50 on the shoe bottom to be relieved each and every time when the leveling roll is located substantially at the junction of the forepart and shank portions of the shoe bottom, or the disk 374 may be utilized with the pins 378, 380 so spaced as to cause no relief of pressure of the leveling roll during the leveling operation or the relief of pressure to occur only during predetermined rearward and forward swinging movements of the jack. As previously pointed out, the sleeves 692, 694 of the control device 633 may be adjusted respectively along the bushing 682 (Figs. 26 and 28) by turning the shafts 708, 710 to vary the positions of the finger pieces 700 and 918. Preferably the arrangement is such that the finger pieces 700, that control the extent of

forward and rearward swinging movements of the jack while the roll is operating in the shank and on the forepart at one side of the shoe bottom, and the finger pieces 918, associated with these finger pieces 700 for determining the time in the forward or rearward swinging movement of the jack when the leveling roll begins its tipping movement at that side of the shoe, are connected to move with one of the sleeves 692, 694, and the finger pieces 700 and 918, for controlling the extent of the forward and rearward swinging movements of the jack and the time in each swinging movement when the roll begins its tipping movement when the roll is operating upon the other side of the shoe bottom, are connected to move with the other one of the sleeves 692, 694. By rotating the shafts 708, 710, the positions of the finger pieces 700 may be varied relatively to the disks 676 and 684 to vary the extent of rearward movement of the jack when the roll is operating on the bottom of the forepart and the extent of forward movement of the jack when the roll is operating in the shank in accordance with variations in length of the foreparts and shank portions of shoes of different styles. It will be readily seen also that by rotation of the shafts 708, 710, the group of finger pieces 700 at one side of the shoe may be positioned relatively to the disks 676 and 684 differently from the group of fingers 700 at the opposite side of the shoe bottom to take care of variations in length of the foreparts and shank portions at the opposite sides of the bottom of the shoe. Since the finger pieces 918 are adjustable with the finger pieces 700, the leveling roll 50 will of course begin its tipping movement in each swinging movement of the jack when the roll is in the same relation to the bottoms of the forepart and shank portions of shoes of different styles. It will be understood further that the direction and extent of tipping movements imparted to the leveling roll in the course of the leveling operation may be varied as desired for operating upon shoes of different styles by varying the positions of the blocks 1074 on the shafts 1050 to 1070 inclusive of the controlling device 802. In the construction herein shown, the positions of the blocks 1074 may be varied by rotation of the shaft 1056, which is geared to the shafts 1054, 1052 and 1050, the shaft 1058, the shaft 1060, which is geared to the shaft 1062, the shaft 1068, which is geared to the shafts 1066 and 1064, and the shaft 1070. In order that the blocks 1074 on the shafts of each group that are controlled by the rotation of one of the shafts of that group, may be moved in the desired direction to act on one or the other of the bars 862, 872 and thus to determine the direction of tipping movement of the leveling roll, and also to the desired extent relatively to the pivoted arm 1006 and thus to determine the extent of tipping movement of the leveling roll, the shafts may be provided with either left or right-hand threads of the same or different leads, or one or more of the shafts may be double or triple threaded.

While the invention has been herein illustrated by reference to control devices 633 and 802 arranged to control the power operation of the machine so as to cause it to perform the cycle of operations illustrated diagrammatically in Fig. 29, it will be understood that the control devices may be arranged to vary the cycle in any desired manner by varying the number of finger pieces 700 and 918 carried by the device 633 and the number of blocks 1074 carried by the device 802.

Thus the total number of swinging movements imparted to the jack or tipping movements imparted to the leveling roll may be varied, or the jack may receive a plurality of swinging movements in opposite directions while the roll is operating upon a particular portion of the shoe bottom where it is desired to treat that portion specially before or after other portions of the shoe bottom are leveled. Where the total number of swinging movements imparted to the jack or tipping movements imparted to the leveling roll are varied it will, of course, be necessary to provide the machine with ratchet plates 754, 756 and 1126, 1128 having the proper number of teeth.

In the operation of the machine, briefly summarized, the operator, after having adjusted the control devices 633 and 802 for the style of shoe to be operated upon, mounts a last and shoe on the supporting jack, swings the jack rearwardly to connect it to the arm 148 and then depresses the starting treadle 630 to impart forward movement to the rod 610 to cause the clutch 518 to be connected to the shaft 156 and to rotate it in the direction to impart rearward swinging movement to the jack. It will be understood that as the jack is swung from its initial shoe receiving position into position to be connected to the arm 148, the toe end of the shoe acts by engagement with the leveling roll 50 to lift it against the weight of the part and that as the jack is swung rearwardly by power, the arm 306 receives a swinging movement in a counterclockwise direction, as viewed in Fig. 1, to straighten the toggle 252, 264 and thus to cause the leveling roll to be pressed yieldingly down on the bottom of the toe end of the sole. As the jack is swung rearwardly, the device 633 moves rearwardly with the jack along the shaft 674 until the disk 676 engages the pin 718 and swings the arm 720 in the direction to operate the above-described mechanism to cause rearward movement to be imparted to the rod 610 to disconnect the clutch 518 and to connect the clutch 520 to the shaft 156 to cause forward swinging movement to be imparted to the jack, the device 633 moving forwardly along the shaft 674 until the finger 728 of one of the finger pieces 730 acts by engagement with the pin 718 to cause the direction of swinging movement of the jack to be reversed. The device 633 is indexed automatically thus to bring one of the finger pieces 730 or one of the shoulder pins 724 into position to engage the pin 718 and to cause the direction of swinging movement of the jack to be reversed at definite points in the operation of the roll on the shoe bottom. In the final forward swinging movement of the jack to cause the roll to return to the toe end of the shoe at the end of the leveling roll, the head of the adjustable screw 736 carried by the arm 656 of the lever 484 (Fig. 3) engages the pin 788 in the latch 648 and lifts the latch to release the rod 610 for forward movement substantially at the time in the forward movement of the device 633 when the pin 718 is engaged by the disk 684, the springs, 690, 692 then acting to centralize the rod 610 with both latches 648, 650 upheld by the roll 654 of the block 634 and both friction clutches 518, 520 disconnected from the shaft 156. It is at this time that the pin 159 is withdrawn to disconnect the jack from the arm 148 to permit the jack to return to its initial starting position.

As the jack is thus swung rearwardly and forwardly by the power means under control of the device 633, the time in each swinging movement

when the leveling roll 50 begins its tipping movement laterally of the shoe is determined by engagement of one of the finger pieces 918 of the device 633 with the pin 916 as previously described. The direction and extent of each tipping movement of the leveling roll is controlled by the device 802, the device 802 being indexed to bring the finger 1076 of the blocks 1074 successively into position to act on one or the other of the bars 862, 872 to determine the direction of tipping movement of the roll and the device 802 being movable along the shaft 1012 in response to the tipping of the leveling roll until the finger 1076 engages and swings the pivoted arm 1066 in the direction to release the lever 804 to the action of the springs 816 to stop the tipping of the roll after it has received a tipping movement of predetermined extent. In order properly to level the outer edge portion of the bottom of the forepart, a continuous tipping movement at a comparatively slow rate is imparted to the leveling roll in response to the forward swinging movement of the jack to cause the roll to traverse that portion of the shoe bottom from the ball line forwardly to the toe end of the sole. As hereinbefore explained, the machine may be used without the disk 374 in which case the relief of pressure of the leveling roll on the shoe bottom will occur each and every time in the operation of the machine when the leveling roll is located substantially at the junction of the forepart and shank portions of the shoe bottom or, if desired, in operating upon shoes of different styles, the disk 374 may be used with the pins 378, 380 so spaced that no relief of pressure of the leveling roll will occur in the operation of the machine or the relief of pressure of the leveling roll at the ball line will occur only in predetermined rearward and forward swinging movements of the shoe supporting jack.

Having described the invention, what I claim as new and desire to secure by Letters Patent of the United States is:

1. In a leveling machine, a leveling tool, a shoe support, power-operated means for effecting relative movements of said support and tool in opposite directions lengthwise of a shoe on the support to cause said tool to operate progressively along the shoe bottom, and means for controlling said power-operated means, said means including a power-operated device automatically movable variable amounts in opposite directions in time relation to the relative movements of the support and tool in opposite directions and arranged by the extent of its movements to determine the extent of the relative movements of the support and tool.

2. In a leveling machine, a leveling tool, a shoe support, power-operated means for moving said shoe support in opposite directions lengthwise of a shoe on the support to cause the leveling tool to operate progressively along the shoe bottom, and means for controlling said power-operated means, said means including a device connected to said shoe support to move simultaneously therewith variable amounts and being arranged by the extent of its movements in opposite directions automatically to determine the extent of the movements of the shoe support in opposite directions.

3. In a leveling machine, a leveling tool, a shoe support, power-operated means for moving said support in opposite directions lengthwise of a shoe on the support to cause the tool to operate progressively along the shoe bottom, and control

means for said power-operated means including a device connected to said shoe support to move simultaneously therewith and arranged to cause the direction of movement of the support to be reversed automatically at several different points in the operation of the tool on the bottom of the shoe.

4. In a leveling machine, a leveling tool, a shoe support, power-operated means for moving said support in opposite directions lengthwise of a shoe on the support to cause the tool to operate progressively along the shoe bottom, a device connected to said shoe support to move simultaneously therewith and arranged to control said power-operated means to cause the direction of movement of the support to be reversed at definite points in the operation of the tool on the bottom of the shoe, and means arranged to act independently of said device to bring said power-operated means to a stop after a predetermined number of movements in opposite directions have been imparted to said shoe support.

5. In a leveling machine, a leveling tool, a shoe support, power-operated means for effecting relative movements of said support and tool in opposite directions lengthwise of a shoe on said support to cause the tool to operate progressively along the shoe bottom, mechanism for starting said power-operated means in operation and for also stopping said power-operated means and for reversing it, and a master-control device for operating said mechanism to stop and reverse said power-operated means at several different predetermined points in the operation of the tool on the bottom of the shoe.

6. In a leveling machine, a leveling tool, a shoe support, power-operated means for effecting relative movements of said support and tool in opposite directions lengthwise of a shoe on the support to cause said tool to operate progressively along the shoe bottom, mechanism for starting said power-operated means in operation and for also stopping said power-operated means and for reversing it, and a control device movable in opposite directions simultaneously with the relative movements of the support and tool in opposite directions for operating said mechanism to stop and reverse said power-operated means at several different predetermined points in the operation of the leveling tool on the bottom of the shoe.

7. In a leveling machine, a leveling tool, a shoe support, power-operated means for effecting relative movements of said support and tool in opposite directions lengthwise of a shoe on the support to cause said tool to operate progressively along the shoe bottom, mechanism for stopping said power-operated means and for reversing it, and an intermittently rotatable device for operating said mechanism to stop and reverse said power-operated means a predetermined number of times in each cycle of the machine to cause a predetermined number of relative movements of said support and tool, said device being movable in opposite directions respectively different predetermined distances between successive movements of rotation to determine the extent of each relative movement of the support and leveling tool.

8. In a leveling machine, a leveling tool, a shoe support, power-operated means for moving said shoe support rearwardly and forwardly beneath said leveling tool to cause the tool to operate progressively along the forepart and shank portions of the bottom of a shoe on said support, a

member movable by the operator for starting said power-operated means in operation, said member being movable thereafter in opposite directions respectively to reverse said power-operated means, a master-control device for thus moving said member to reverse said power-operated means, said device comprising a sleeve movable in opposite directions in time relation to the rearward and forward movements of said support, a pair of spaced disks on said sleeve for effecting movement of said member in opposite directions respectively, one of said disks being arranged to limit rearward movement of the support when the tool is operating in the shank portion of the shoe and the other one of said disks being arranged to limit forward movement of the support when the tool is operating on the forepart, a plurality of sets of angularly disposed abutments mounted on said sleeve between said disks, and means for intermittently rotating said sleeve to bring said abutments successively into operative relation to said member, one set of said abutments being arranged to limit forward movement of the support when the tool is operating in the shank portion of the shoe bottom and the other set of said abutments being arranged to limit rearward movement of the support when the tool is operating along the bottom of the forepart.

9. In a leveling machine, a leveling tool, a shoe support, power-operated means for effecting relative movements of said support and tool lengthwise of a shoe on the support to cause the tool to operate progressively along the shoe bottom, and reciprocating mechanism for automatically reversing said power-operated means a plurality of times at several different predetermined points to cause a predetermined number of relative movements of predetermined extent of said support and leveling tool in the course of the leveling operation.

10. In a leveling machine, a leveling tool, a shoe support, power-operated means for moving said shoe support forwardly and rearwardly relatively to said leveling tool to cause the tool to operate progressively along the shoe bottom, a member for controlling said power-operated means arranged to be moved by the operator to start the movements of the support, said member being thereafter movable in opposite directions to cause the movements of the support to be reversed, and automatic means for operating said starting member a predetermined number of times in time relation to the movements of the support to cause a predetermined number of forward and rearward movements of predetermined extent to be imparted to said shoe support in the course of the leveling operation.

11. In a leveling machine, a leveling tool and a shoe support relatively movable in directions lengthwise of a shoe on the support to cause the leveling tool to operate progressively along the shoe bottom, power-operated means for effecting such relative movements of the support and tool, and an intermittently movable device for automatically controlling said power-operated means to determine the number of relative movements of said support and leveling tool and the extent of each relative movement.

12. In a leveling machine, a leveling tool, a shoe support, power-operated means for imparting to said shoe support movements in opposite directions lengthwise of a shoe thereon to cause said tool to operate progressively along the shoe bottom, a member for starting said power-oper-

ated means in operation, said member being movable in one direction to start said power-operated means and in opposite directions thereafter to reverse it, and a power-operated device for determining the cycle of operations of the machine by control of said starting member, said device including several variably spaced abutments movable successively into positions to move said starting member alternately in opposite directions in time relation to the movements of the shoe support and thus to determine the extent of each movement of the support.

13. In a leveling machine, a leveling tool, a shoe support, power-operated means for imparting to said shoe support movements in opposite directions lengthwise of a shoe thereon to cause said tool to operate progressively along the shoe bottom, mechanism for starting said power-operated means and for reversing it including a member movable in one direction to start said means and in opposite directions thereafter to reverse it, a power-operated device for thus moving said member to reverse said power-operated means, said device being movable in opposite directions respectively in time relation to the movements of the support in opposite directions, a plurality of circumferentially spaced abutments mounted on said device for effecting movements of said member alternately in opposite directions, and means for intermittently rotating said device to bring said abutments successively into operative positions.

14. In a leveling machine, a leveling tool, a shoe support, power-operated means for moving said shoe support rearwardly and forwardly beneath said leveling tool to cause the tool to operate progressively along the bottom of a shoe on said support, said leveling tool being mounted for tipping movements laterally of the shoe to vary its inclination in operating upon different portions of the shoe bottom, mechanism for starting said power-operated means and for reversing it including a member movable in one direction to cause the support to be moved rearwardly and in the opposite direction to cause forward movement of the support, a master control device for thus moving said member to reverse the power-operated means, said device comprising a sleeve movable in opposite directions in time relation to the rearward and forward movements of the support, a pair of spaced disks on said sleeve for effecting movement of said member in opposite directions respectively, one of said disks being arranged to limit the rearward movement of the support when the tool is operating in the shank portion and the other one of said disks being arranged to limit forward movement of the support when the tool is operating on the forepart, a plurality of sets of angularly disposed abutments mounted on said sleeve between said disks, and means for intermittently rotating said sleeve to bring said abutments successively into positions to operate said member, said sets of abutments being arranged respectively to limit forward movement of the support when the tool is operating in the shank portion and rearward movement of the support when the tool is operating on the forepart in accordance with variations in length of the forepart and shank portions at the opposite sides of the shoe bottom.

15. In a leveling machine, a leveling tool, a shoe support, a power-operated means for moving said shoe support rearwardly and forwardly

beneath said leveling tool to cause the tool to operate progressively along the bottom of a shoe on said support, mechanism for starting said power-operated means and for reversing it including a member movable in one direction to cause the support to be moved rearwardly and in the opposite direction to cause forward movement of the support, a master control device for thus moving said member to reverse the power-operated means, said device comprising a sleeve movable in opposite directions in time relation to the rearward and forward movements of the support, a pair of spaced disks on said sleeve for effecting movement of said member in opposite directions respectively, one of said disks being arranged to limit the rearward movement of the support when the tool is operating in the shank portion and the other one of said disks being arranged to limit forward movement of the support when the tool is operating on the forepart, a plurality of sets of angularly disposed abutments mounted on said sleeve between said disks, and means for intermittently rotating said sleeve to bring said abutments successively into operative relation to said member, said sets of abutments being arranged respectively to limit forward movement of the support when the tool is operating in the shank portion and rearward movement of the support when the tool is operating on the forepart and being relatively adjustable to take care of the variations in length of the foreparts and shank portions of shoes of different styles.

16. In a leveling machine, a leveling tool, a shoe support, power-operated means for moving said shoe support in opposite directions lengthwise of a shoe thereon to cause said leveling tool to operate progressively along the shoe bottom, and means for controlling said power-operated means comprising parts movable by the operator to start said power-operated means in operation and other parts operative in response to the movements of the shoe support for reversing said power-operated means at several different points spaced lengthwise of the shoe in the operation of the tool on the bottom of the shoe.

17. In a leveling machine, a leveling tool and a shoe support relatively movable in opposite directions lengthwise of a shoe on the support to cause the leveling tool to operate progressively along the shoe bottom, power-operated means for effecting such relative movements, and means for controlling said power-operated means comprising parts movable by the operator to start said power-operated means in operation and other parts operative in response to relative movements of the support and tool for reversing said power-operated means at definite points in the operation of the tool on the bottom of the shoe and for bringing said power-operated means to a stop after a predetermined number of relative movements of said support and tool.

18. In a leveling machine, a leveling tool, a shoe support, power-operated means for moving said shoe support in opposite directions lengthwise of a shoe thereon to cause said leveling tool to operate progressively along the shoe bottom, and means for controlling said power-operated means comprising a member movable by the operator to start said power-operated means in operation, said member being movable to reverse said power-operated means, and a device movable in opposite directions respectively in response to movements of the support in opposite directions for operating said member to reverse said power-operated means at several different variably

spaced points in the operation of the tool on the bottom of the shoe.

19. In a leveling machine, a leveling tool, a shoe support, power-operated means for moving said shoe support in opposite directions lengthwise of a shoe thereon to cause said leveling tool to operate progressively along the shoe bottom, and means for controlling said power-operated means comprising a member movable by the operator to start said power-operated means in operation, said member being movable to reverse said power-operated means, and a device movable in opposite directions respectively in response to movements of the shoe support in opposite directions and arranged to cause said member to be moved first reversely and thereafter in opposite directions alternately a plurality of times to cause a plurality of movements of different predetermined extents to be imparted to said shoe support in opposite directions.

20. In a leveling machine, a leveling tool, a shoe support, power-operated means for moving said shoe support in opposite directions lengthwise of a shoe thereon to cause said leveling tool to operate progressively along the shoe bottom, means for controlling said power-operated means comprising a member movable by the operator to start said power-operated means in operation, said member having a neutral position and reversing positions, a device for operating said member to reverse said power-operated means a plurality of times to cause a plurality of movements in opposite directions to be imparted to said shoe support, and means for moving said member to neutral position to stop said power-operated means after a predetermined number of movements in opposite directions have been imparted to said shoe support.

21. In a leveling machine, a leveling tool and a shoe support relatively movable in opposite directions lengthwise of a shoe on the support to cause the leveling tool to operate progressively along the shoe bottom, power-operated means for effecting such relative movements, means for controlling said power-operated means comprising a member movable by the operator to start said power-operated means in operation, said member being movable to stop and reverse said power-operated means, a device mounted for movements in opposite directions respectively in response to relative movements of the support and tool in opposite directions for operating said member to reverse said power-operated means a plurality of times in the power-operation of the machine to determine the cycle of relative movements of the shoe support and leveling tool, and means for bringing said power-operated means automatically to a stop after a predetermined number of relative movements of said support and tool.

22. In a leveling machine, a leveling tool and a shoe support relatively movable in opposite directions lengthwise of a shoe on the support to cause the tool to operate progressively along the shoe bottom, power-driven means for effecting such relative movements, oppositely acting clutches for moving said power-driven means in opposite directions respectively, a clutch control member movable in one direction to connect one of said clutches and the power-driven means and in the opposite direction to disconnect that clutch and to connect the oppositely acting clutch, operator-controlled means for moving said clutch control member in one direction to start said power-driven means in operation, and means for imparting to said clutch control member automatically

movements in opposite directions alternately in time relation to the relative movements of the support and tool to cause a predetermined number of relative movements of predetermined extent to be imparted to said support and tool in the course of the leveling operation.

23. In a leveling machine, a leveling tool and a shoe support relatively movable in opposite directions lengthwise of a shoe on the support to cause the leveling tool to operate progressively along the shoe bottom, power-driven means for effecting such relative movements, oppositely acting clutches for moving said power-driven means in opposite directions respectively, and controlling mechanism comprising a member movable by the operator in one direction to connect one of said clutches and the power-driven means, said member being movable reversely to disconnect that clutch and to connect the other clutch and the power-driven means, and means including a device movable rectilinearly in opposite directions in time relation to the relative movements of the support and tool in opposite directions for operating said member to disconnect one of said clutches and the power-driven means and to connect the other clutch thereto at several different predetermined points in the relative movements of the support and tool.

24. In a leveling machine, a leveling tool and a shoe support relatively movable in opposite directions lengthwise of a shoe on the support to cause the leveling tool to operate progressively along the shoe bottom, power-driven means for effecting such relative movement, oppositely acting friction clutches for operating said power-driven means, a member for controlling said friction clutches, said member being movable in one direction to connect one of said clutches and the power-driven means and in the opposite direction to disconnect that clutch and to connect the oppositely acting clutch, a power-operated device for thus moving said clutch control member in time relation to the relative movements of the support and tool a predetermined number of times in the course of the leveling operation, brake means for stopping said power-driven means, and means for operating said brake means to stop and release said power-driven means in response to each movement of said clutch control member to disconnect one of said friction clutches and to connect the oppositely acting clutch.

25. In a leveling machine, a leveling tool, a shoe support, power-operated means for moving said shoe support in directions lengthwise of a shoe thereon to cause said leveling tool to operate progressively along the shoe bottom, and a master control device connected to said shoe support to move simultaneously therewith for determining the cycle of operations of the machine by control of said power-operated means, said control device including means for causing said shoe support to move different amounts during the cycle of operations, said control device being so mounted as to permit it to be readily removed and replaced by a different device for determining a different cycle of operations.

26. In a leveling machine, a leveling tool, a shoe support, power-operated means for moving said shoe support relatively to said leveling tool in directions lengthwise of a shoe on the support to cause the tool to operate progressively along the shoe bottom, a member for starting said power-operated means in operation, said member being movable in one direction thus to start said

power-operated means and in opposite directions thereafter to reverse it, and a master control device for determining the cycle of operations of the machine by control of said starting member, said device being mounted for ready removal and replacement by a different device for determining a different cycle of operations.

27. In a leveling machine, a leveling tool, a shoe support, power-operated means for moving said shoe support rearwardly and forwardly beneath said leveling tool to cause the tool to operate progressively along the bottom of a shoe on the support, a member for starting said power-operated means in operation, said member being movable in one direction thus to start said power-operated means and in opposite directions thereafter to reverse it, a master control device for determining the cycle of operations of the machine by control of said starting member, said device being mounted for ready removal and replacement by a different device for determining a different cycle of operations, and means for bringing the machine automatically to a stop after a predetermined amount of rearward and forward movement has been imparted to the shoe support if the machine is inadvertently started when no control device is in the machine.

28. In a leveling machine, a leveling roll, a shoe support, power-operated means for effecting relative movement of said shoe support and leveling roll in opposite directions lengthwise of a shoe on the support to cause the roll to operate progressively along the bottom of the shoe, additional power-operated means for imparting to said leveling roll tipping movements in opposite directions laterally of the shoe to vary its inclination in operating upon different portions of the shoe bottom, mechanism for controlling both said power-operated means to cause a predetermined number of relative movements of predetermined extent of said support and roll in the course of the leveling operation and to determine the time in each relative movement when the leveling roll begins its tipping movement, and separate mechanism for controlling said additional power-operated means to determine the direction and extent of each tipping movement of the leveling roll.

29. In a leveling machine, a leveling tool and a shoe support relatively movable in opposite directions lengthwise of a shoe on said support to cause the tool to operate progressively along the shoe bottom, power-operated means for tipping said leveling tool in opposite directions laterally of the shoe, means for starting said power-operated means in operation at definite points in the operation of the tool on the bottom of the shoe, and means for bringing said power-operated means to a stop each time it is thus started after a tipping movement of predetermined extent in a predetermined direction has been imparted to said leveling tool.

30. In a levelling machine, a leveling tool, a shoe support mounted for swinging movements in opposite directions lengthwise of a shoe thereon to cause said tool to operate progressively along the shoe bottom, power-operated means for tipping said leveling tool laterally of the shoe to vary its inclination in operating upon different portions of the shoe bottom, means for starting said power-operated means in operation at a predetermined time in each swinging movement of the support, and separate means for controlling said power-operated means to determine the direction and extent of each tipping movement of the tool.

31. In a leveling machine, a leveling tool and a

shoe support relatively movable in directions lengthwise of a shoe on the support to cause said leveling tool to operate progressively along the shoe bottom, power-operated means for tipping said leveling tool in opposite directions laterally of the shoe, means operating in time relation to the relative movements of the support and tool for starting said power-operated means in operation at definite times in the operation of the tool on the bottom of the shoe, and a power-operated device for bringing said power-operated means to a stop each time it is thus started after a tipping movement of predetermined extent in a predetermined direction has been imparted to said leveling tool.

32. In a leveling machine, a leveling tool and a shoe support relatively movable in directions lengthwise of a shoe on the support to cause the leveling tool to operate progressively along the shoe bottom, power-operated means for tipping said leveling tool in opposite directions laterally of the shoe, a device movable in opposite directions respectively in time relation to the relative movements of the support and tool in opposite directions lengthwise of the shoe for starting said power-operated means in operation at a definite time in each relative movement of the support and tool, and a second device for selectively determining the direction of each tipping movement of the leveling tool, said second device being movable in opposite directions in response to tipping movements of the leveling tool in opposite directions and being arranged by the extent of its movement in each direction to determine the extent of the tipping movement of the leveling tool by control of said power-operated means.

33. In a leveling machine, a leveling tool, a shoe support mounted for movements in opposite directions lengthwise of a shoe thereon to cause the tool to operate progressively along the shoe bottom, power-operated means for tipping said leveling tool in opposite directions laterally of the shoe, means for starting said power-operated means in operation at definite points in the operation of the tool on the bottom of the shoe, and means for adjustably determining the direction and extent of each tipping movement of the tool.

34. In a leveling machine, a leveling tool and a shoe support relatively movable in opposite directions lengthwise of a shoe on said support to cause the tool to operate progressively along the shoe bottom, power-operated means for tipping the leveling tool in opposite directions laterally of the shoe, means for starting said power-operated means in operation at definite points in the operation of the tool on the bottom of the shoe, and a device for determining the direction and extent of each tipping movement of the leveling tool by control of said power-operated means.

35. In a leveling machine, a leveling tool and a shoe support relatively movable in opposite directions lengthwise of a shoe on said support to cause the tool to operate progressively along the shoe bottom, power-operated means for tipping said leveling tool in opposite directions laterally of the shoe, means for starting said power-operated means in operation at definite points in the operation of the tool on the bottom of the shoe, and controlling means for bringing said power-operated means to a stop each time it is thus started comprising a device for determining the direction of each tipping movement of the tool, said device being movable simultaneously with the tool and being arranged by the extent

of its movement to determine the extent of each tipping movement of the tool.

36. In a leveling machine, a leveling tool, a shoe support mounted for swinging movements in opposite directions lengthwise of a shoe thereon to cause the tool to operate progressively along the shoe bottom, power-operated means for tipping said leveling tool in opposite directions laterally of the shoe, a device connected to said shoe support to move simultaneously therewith and arranged to start said power-operated means in operation at a predetermined time in each swinging movement of said support, and additional means for controlling said power-operated means to determine the direction and extent of each tipping movement of the leveling tool.

37. In a leveling machine, a leveling tool, a shoe support mounted for swinging movements in opposite directions lengthwise of a shoe thereon to cause the tool to operate progressively along the shoe bottom, power-operated means for tipping said tool in opposite directions laterally of the shoe, a device connected to said shoe support to move simultaneously therewith and arranged to start said power-operated means in operation at a predetermined time in each swinging movement of the support, and a second device for determining the direction of each tipping movement of the tool, said second device being movable simultaneously with the tool and being arranged to bring said power-operated means to a stop after a tipping movement of adjustably variable extent has been imparted to said leveling tool.

38. In a leveling machine, a leveling tool and a shoe support relatively movable in opposite directions lengthwise of a shoe on the support to cause the tool to operate progressively along the shoe bottom, power-operated means for tipping the leveling tool in opposite directions laterally of the shoe, and a device connected to said leveling tool to move simultaneously therewith and arranged by the extent of its movements in opposite directions respectively to determine the extent of the tipping movements of the leveling tool in opposite directions by control of said power-operated means.

39. In a leveling machine, a leveling roll, a shoe support, power-operated means for effecting relative movement of said support and roll in opposite directions lengthwise of a shoe on the support to cause the roll to operate progressively along the shoe bottom, a second power-operated means for tipping said roll in opposite directions laterally of the shoe, a device for controlling both said power-operated means to cause a predetermined number of relative movements of predetermined extent of said support and roll lengthwise of the shoe and to determine the time in each relative movement when the leveling roll begins its tipping movement, and a second device for determining the direction and extent of each tipping movement of the roll by control of said second power-operated means.

40. In a leveling machine, a leveling tool, a shoe support, power-operated means for swinging said shoe support in opposite directions lengthwise of a shoe thereon to cause the tool to operate progressively along the shoe bottom, a second power-operated means for tipping said leveling tool in opposite directions laterally of the shoe, a device connected to said shoe support to move simultaneously therewith for controlling said first-named power-operated means to cause a predetermined number of swinging

movements of predetermined extent to be imparted to said shoe support, mechanism arranged to be operated by said device for starting said second power-operated means in operation at a predetermined time in each swinging movement of the support, and a second device for controlling said mechanism to determine the direction of each tipping movement of the tool and for bringing said second power-operated means to a stop after a tipping movement of predetermined extent has been imparted to said leveling tool.

41. In a leveling machine, a leveling tool and a shoe support relatively movable in opposite directions lengthwise of a shoe on the support to cause the leveling tool to operate progressively along the shoe bottom, power-operated means for tipping said leveling tool in opposite directions laterally of the shoe, automatically controlled clutch means for starting said power-operated means in operation at a predetermined time in each relative movement of the support and tool, and controlling means for said power-operated means arranged to determine automatically the direction and extent of each tipping movement of said leveling tool.

42. In a leveling machine, a leveling tool and a shoe support relatively movable in opposite directions lengthwise of a shoe on the support to cause the tool to operate progressively along the shoe bottom, said leveling tool being mounted for tipping movements in opposite directions laterally of the shoe, and means for imparting to the leveling tool in response to the relative movement of the support and tool a continuous tipping movement in a predetermined direction in operating upon a portion of the bottom of the shoe.

43. In a leveling machine, a leveling tool and a shoe support relatively movable in opposite directions lengthwise of a shoe on the support to cause the tool to operate progressively along the shoe bottom, means for imparting to said leveling tool tipping movements of different extents in opposite directions laterally of the shoe at definite points in the operation of the tool on the bottom of the shoe, and means arranged to act through said last-named means to cause a continuous tipping movement laterally of the shoe to be imparted to said leveling tool in response to the relative movement of the support and tool in operating along a selected portion of the bottom of the shoe.

44. In a leveling machine, a leveling tool and a shoe support relatively movable in opposite directions lengthwise of a shoe on the support to cause the tool to operate progressively along the shoe bottom, means for imparting to said leveling tool tipping movements of different extents in opposite directions laterally of the shoe at definite points in the operation of the tool on the bottom of the shoe, and means for tipping the leveling tool continuously in response to relative movement of the support and tool as the tool is operating along a predetermined portion of the shoe bottom.

45. In a leveling machine, a leveling tool and a shoe support relatively movable in opposite directions lengthwise of a shoe on the support to cause the tool to operate progressively along the shoe bottom, means arranged to act automatically at different points in the operation of the tool on the bottom of the shoe to impart to the tool at a comparatively rapid rate a tipping movement of predetermined extent in a predetermined direction, and means for tipping the leveling tool con-

tinuously at a comparatively slow rate during the operation of the tool upon a selected portion of the shoe bottom, said last-named means being adjustable to vary the rate at which the leveling tool is thus tipped.

46. In a leveling machine, a leveling tool, a shoe support movable in directions lengthwise of a shoe thereon to cause the leveling tool to operate progressively along the shoe bottom, means for tipping the leveling tool different distances laterally of the shoe at different points in the operation of the tool on the bottom of the shoe, and means for connecting said tool-tipping means and the shoe support to cause a continuous tipping movement to be imparted to the leveling tool proportional to the extent of movement of the shoe support as the tool is operating along a predetermined portion of the bottom of the shoe.

47. In a leveling machine, a leveling tool, a shoe support movable in directions lengthwise of a shoe thereon to cause the leveling tool to operate progressively along the shoe bottom, means for tipping the leveling tool at a comparatively rapid rate to vary its inclination in operating on different portions of the bottom of the shoe, and automatic means for connecting the tool-tipping means and the shoe support at a predetermined time in the movement of the support to cause the tool to be tipped continuously at a comparatively slow rate while the tool is operating along a predetermined portion of the shoe bottom.

48. In a leveling machine, a leveling tool, a shoe support movable in directions lengthwise of a shoe on the support to cause said leveling tool to operate progressively along the shoe bottom, power-operated means for thus moving the shoe support, mechanism for tipping the leveling tool in opposite directions laterally of the shoe to vary its inclination in operating upon different portions of the shoe bottom, and means for connecting said tool-tipping mechanism and said power-operated means at a predetermined time in the movement of the shoe support to cause a continuous tipping movement to be imparted to said leveling tool as the tool is operating along a selected portion of the shoe bottom.

49. In a leveling machine, a leveling tool, a shoe support, power-operated means for moving said shoe support in opposite directions lengthwise of a shoe thereon to cause said tool to operate progressively along the bottom of the shoe in a predetermined cycle and for also imparting to said leveling tool a continuous tipping movement in a predetermined direction during the operation of the tool along a selected portion of the shoe bottom, and additional power-operated means for tipping the leveling tool laterally of the shoe to vary its inclination in operating upon other portions of the bottom of the shoe.

50. In a leveling machine, a leveling tool, a shoe support movable relatively to said leveling tool in directions lengthwise of a shoe on the support to cause the tool to operate progressively along the shoe bottom, mechanism for tipping said leveling tool in opposite directions laterally of the shoe, power-operated means for operating said tool-tipping mechanism at definite points in the operation of the tool on the bottom of the shoe to vary its inclination in operating upon different portions of the shoe bottom, and automatic means for connecting said tool-tipping mechanism and the shoe support to

cause a continuous tipping movement in a predetermined direction to be imparted to said leveling tool in response to the movement of the shoe support in operating along a predetermined portion of the bottom of the shoe.

51. In a leveling machine, a leveling roll, a shoe support movable in opposite directions lengthwise of a shoe on the support to cause the roll to operate progressively along the shoe bottom, means for tipping said leveling roll in opposite directions laterally of the shoe, power-operated means for operating said roll-tipping means at definite points in the operation of the roll on the bottom of the shoe to vary the inclination of the roll in operating upon different portions of the shoe bottom, and additional means for operating said roll-tipping means continuously while the roll is operating upon a predetermined portion of the bottom of the shoe.

52. In a leveling machine, a leveling roll, a shoe support movable in opposite directions lengthwise of a shoe thereon to cause the roll to operate progressively along the shoe bottom, means for tipping the leveling roll in opposite directions laterally of the shoe, and automatic mechanism for operating said roll-tipping means at different times and at different rates of speed in the course of the leveling operation, said mechanism comprising parts arranged to be operated by power at a comparatively rapid rate to vary the inclination of the roll in operating upon different portions of the shoe bottom and other parts arranged to be connected to said shoe support while said power-operated parts are stationary to cause the leveling roll to be tipped continuously while the roll is operating along a predetermined portion of the shoe bottom.

53. In a leveling machine, a leveling roll, a shoe support movable in directions lengthwise of a shoe thereon to cause the leveling roll to operate progressively along the shoe bottom, mechanism for tipping the leveling roll in opposite directions laterally of the shoe, and means for connecting said roll-tipping mechanism and the shoe support to cause a continuous tipping movement to be imparted to said leveling roll in response to the movement of the support.

54. In a leveling machine, a leveling roll, a shoe support movable in directions lengthwise of a shoe thereon to cause the leveling roll to operate progressively along the shoe bottom, mechanism for tipping the leveling roll in opposite directions laterally of the shoe, a power-operated member for operating said roll-tipping mechanism at definite points in the operation of the roll on the bottom of the shoe to vary the inclination of the roll in operating upon different portions of the shoe bottom, a second power-operated member for moving said shoe support in opposite directions lengthwise of the shoe, and means for automatically connecting said second power-operated member and the roll-tipping mechanism when said first-named power-operated member is stationary to cause a continuous tipping movement to be imparted to said leveling roll in operating upon a selected portion of the shoe bottom.

55. In a leveling machine, a leveling roll, a shoe support movable in opposite directions lengthwise of a shoe thereon to cause the leveling roll to operate progressively along the shoe bottom, mechanism for tipping the leveling roll in opposite directions laterally of the shoe, and means for connecting said roll-tipping mechanism and the shoe support to cause the roll to be tipped continu-

ously in response to the movement of the shoe support, said means comprising a member movable in opposite directions in response to the movements of the support in opposite directions, a lever for connecting said member and the roll-tipping mechanism, a latch for holding said lever normally in an inoperative position, and a device for operating said latch to release said lever for movement into position to be connected to said member at a predetermined time in the movement of said shoe support.

56. In a leveling machine, a leveling tool and a shoe support relatively movable in directions lengthwise of a shoe on the support to cause the leveling tool to operate progressively along the shoe bottom, said leveling tool being arranged to be positioned heightwise of the shoe initially for the leveling operation by engagement of the toe end of the shoe therewith, and means for pressing the leveling tool yieldingly on the bottom of the shoe only after it has been thus positioned.

57. In a leveling machine, a leveling tool, a shoe support movable in directions lengthwise of a shoe thereon to cause the leveling tool to operate progressively along the shoe bottom, said leveling tool being arranged to be positioned heightwise of the shoe initially for the leveling operation by engagement of the toe end of the shoe therewith, and means for pressing the leveling tool yieldingly on the bottom of the shoe only after it has been thus positioned.

58. In a leveling machine, a leveling tool, a shoe support movable in directions lengthwise of a shoe thereon to cause the leveling tool to operate progressively along the shoe bottom, said leveling tool being mounted to swing freely heightwise of the shoe into a position determined by engagement of the toe end of the shoe therewith, and means for pressing the leveling tool yieldingly on the bottom of the shoe after it has thus been positioned by the shoe.

59. In a leveling machine, a leveling tool, a shoe support movable in directions lengthwise of a shoe thereon to cause the leveling tool to operate progressively along the shoe bottom, spring means for pressing the leveling tool upon the bottom of the shoe, and means for rendering said spring means ineffective thus to act on the tool, said tool being arranged to be positioned heightwise of the shoe by engagement of the toe end of the shoe therewith before any substantial pressure is applied by the tool on the bottom of the shoe.

60. In a leveling machine, a leveling tool, a shoe support, means for moving said shoe support in directions lengthwise of a shoe thereon to cause said leveling tool to operate progressively along the shoe bottom, spring means for pressing the leveling tool down on the bottom of the shoe, and automatic means for relieving said tool completely from the force of said spring means, the tool being arranged when thus relieved to be lifted by the shoe into position to contact with the bottom face of the toe end of the shoe sole prior to the operation of the tool on the bottom of the shoe.

61. In a leveling machine, a leveling tool, a shoe support movable in directions lengthwise of a shoe thereon to cause the leveling tool to operate progressively along the shoe bottom, spring means for pressing the leveling tool yieldingly on the shoe, a lever for controlling said spring means, and a stop for engaging said lever initially to release the tool from the force of said spring means to permit the tool to be positioned heightwise of

the shoe by engagement of the toe end of the shoe therewith prior to the operation of the tool on the shoe.

62. In a leveling machine, a leveling tool, a shoe support movable in directions lengthwise of a shoe thereon to cause the leveling tool to operate progressively along the shoe bottom, spring means for pressing the leveling tool yieldingly on the shoe, a lever for controlling said spring means, a stop arranged by engagement with said lever to release the tool completely from the force of said spring means to permit the tool to be positioned heightwise of the shoe by engagement of the toe end of the shoe therewith, and cam-controlled means for moving said lever out of engagement with said stop to render said spring means effective on the tool after the tool has been thus positioned.

63. In a leveling machine, a leveling tool, a shoe support movable in opposite directions lengthwise of a shoe thereon to cause the leveling tool to operate progressively along the shoe bottom, a holder supporting said tool and movable heightwise of the shoe to press the tool upon the shoe and to relieve the pressure, and mechanism for controlling said holder comprising a spring, a pair of levers for applying the force of said spring to the holder, a toggle connecting said levers, and a cam for controlling said toggle, said cam being so shaped as to permit the spring to hold said toggle initially broken to release the holder from the force of said spring to permit the tool to be positioned heightwise of the shoe by engagement of the toe end of the shoe therewith prior to the operation of the tool on the bottom of the shoe.

64. In a leveling machine, a leveling tool and a shoe support relatively movable in directions lengthwise of a shoe on the support to cause the tool to operate progressively along the shoe bottom, automatic means for pressing the tool upon the shoe and for releasing the tool from pressure at a predetermined time in each relative movement of the support and tool, and means for rendering said last-named means ineffective to release the tool from pressure during predetermined relative movements of the support and tool.

65. In a leveling machine, a leveling tool and shoe support relatively movable in directions lengthwise of a shoe on the support to cause the tool to operate progressively along the shoe bottom, cam-controlled mechanism including a spring for pressing the tool on the bottom of the shoe and for relieving the pressure at a predetermined time in each relative movement of the support and tool, and automatic means for controlling said mechanism independently of the cam to cause a relief of pressure to occur only in the course of predetermined relative movements of the support and tool.

66. In a leveling machine, a leveling tool, a shoe support movable in directions lengthwise of a shoe thereon to cause the leveling tool to operate progressively along the shoe bottom, a holder supporting said tool and movable heightwise of the shoe, mechanism for controlling said holder to press the tool on the shoe and to relieve the pressure, said mechanism comprising a spring, a toggle for transmitting the force of said spring to said holder, and a cam for controlling said toggle, said cam being so shaped as to cause said toggle to be held initially broken with said holder released from the force of said spring to permit the leveling tool to be lifted by engagement of the

toe end of the shoe therewith from a position lower than it occupies in operating on the shoe into engagement with the bottom face of the toe end of the shoe sole prior to the operation of the tool on the shoe.

67. In a leveling machine, a leveling tool, a shoe support movable in directions lengthwise of a shoe thereon to cause the leveling tool to operate progressively along the shoe bottom, a holder supporting said tool and movable heightwise of the shoe, mechanism for controlling said holder to press the tool on the shoe and to relieve the pressure, said mechanism comprising a spring, a pair of arms for transmitting the force of said spring to said holder, a toggle connecting said arms, a cam for controlling said toggle, said cam being so shaped as to cause said spring to hold the toggle initially broken with the holder released from the force of said spring to permit the tool to be lifted by engagement of the toe end of the shoe therewith prior to the operation of the tool on the shoe, and a stop arranged to be engaged by one of said arms to hold the spring under stress with the holder thus released.

68. In a leveling machine, a leveling tool and a shoe support relatively movable in directions lengthwise of a shoe on the support to cause the tool to operate progressively along the shoe bottom, spring means for pressing the tool on the bottom of the shoe, a pair of levers for applying the force of said spring means to the leveling tool, a toggle connecting said levers, a stop arranged to be engaged by one of said levers with said toggle broken to hold said spring means initially under stress with said leveling tool released entirely from the force of said spring means to permit the tool to be positioned heightwise of the shoe by engagement of the toe end of the shoe therewith before any substantial pressure is applied by the tool on the shoe, and a cam for moving said toggle into a substantially straightened condition to render said spring means effective on the tool after the tool has been thus positioned.

69. In a leveling machine, a leveling tool, a shoe support movable rearwardly and forwardly beneath said leveling tool to cause the tool to operate progressively along the shoe bottom, spring means for pressing said tool down on the bottom of the shoe, a pair of arms for transmitting the force of said spring means to said tool, a cam-operated toggle connecting said arms and arranged to release said tool from the force of said spring means each time in the movement of the shoe support when the tool is located substantially at the junction of the forepart and shank portions of the shoe bottom, and means for controlling said toggle independently of said cam to cause no release of the tool during predetermined rearward or forward movements of the shoe support.

70. In a leveling machine, a shoe support constructed to receive a shoe bottom upward with its toe end pointing rearwardly, a leveling roll, power-operated means for imparting to said shoe support first a rearward movement and thereafter movements in opposite directions to cause the roll to operate progressively along the shoe bottom, spring means for pressing the roll yieldingly down on the shoe, and automatic means for rendering said spring means thus effective on the roll only after the roll has been lifted by the shoe from an initial position lower than it occupies in operating on the shoe into engagement with the bottom face of the toe end of the shoe sole in the first rearward movement of

75 the support and for releasing the roll from the force of said spring means when the shoe support in its forward movement arrives in a position in which the roll is again in engagement with the toe end of the sole.

71. In a leveling machine, a shoe support constructed to receive a shoe bottom upward with its toe end pointing rearwardly, a leveling roll, power-operated means for imparting to said shoe support first a rearward movement and thereafter movements in opposite directions to cause the roll to operate progressively along the shoe bottom, spring means for pressing the roll down on the shoe, a pair of arms for transmitting the force of said spring means to the roll, toggle links connecting said arms, and means for moving said toggle links into substantially parallel relation to render said spring means effective on the roll after the roll has been lifted by the shoe from an initial position lower than it occupies in operating on the shoe into engagement with the bottom face of the toe end of the shoe sole in the first rearward movement of the support, said last-named means being arranged to release the toggle links for movement into non-parallel relation to cause the roll to be released from the force of said spring means when the shoe support in its forward movement arrives in a position in which the roll is again in engagement with the toe end of the sole.

72. In a leveling machine, a leveling tool and a shoe support relatively movable in directions lengthwise of a shoe on the support to cause the leveling tool to operate progressively along the shoe bottom, spring means for pressing the tool on the bottom of the shoe, a pair of arms for transmitting the force of said spring means to said tool, a stop arranged by engagement with one of said arms to hold said spring means under stress with said tool released entirely from the force of said spring means, a toggle connecting said arms, a cam for controlling the movements of said toggle into and out of substantially straightened condition to render said spring means effective on said tool and to release said tool from the force of said spring means at predetermined times in the operation of the machine, and means for controlling said toggle independently of said cam to vary the times in 50 the operation of the machine when the leveling tool is thus released.

73. In a leveling machine, a leveling tool, a shoe support movable in directions lengthwise of a shoe thereon to cause said leveling tool to operate progressively along the shoe bottom, spring means for pressing said leveling tool on the bottom of the shoe, a pair of arms for transmitting the force of said spring means to said tool, a stop arranged by engagement with one of said arms to hold said spring means under stress with said tool released entirely from the force of said spring means, means operating in time relation to the movements of said support for moving said arm out of engagement with said stop to render said spring means effective on the tool, said means being constructed to release the arm for movement into engagement with said stop to relieve the pressure of the tool on the shoe each time in the movement of the support when the leveling tool is located substantially at the junction of the forepart and shank portions of the shoe bottom, and an automatically controlled member for locking said arm against movement in the direction to engage said stop to cause said tool to be held continu-

ously under pressure during predetermined movements of the shoe support.

74. In a leveling machine, a leveling tool, a shoe support movable in directions lengthwise of a shoe thereon to cause said leveling tool to operate progressively along the shoe bottom, spring means for pressing the tool on the shoe, an arm for transmitting the force of said spring means to said tool, a stop arranged by engagement with said arm to hold said spring means under stress with said tool released entirely from the force of said spring means, means operating in time relation to the movements of said support for moving said arm out of engagement with said stop to render said spring means effective on

5 said tool, said means being constructed to release the arm for movement into engagement with the stop to relieve the pressure of the tool on the shoe each time in the movement of the support when the leveling tool is located substantially at the junction of the forepart and shank portions of the shoe bottom, a member 10 for locking said arm against movement in the direction to engage said stop, and a device rotatable intermittently in time relation to the movements of the shoe support for operating said locking member at selected times to cause no pressure relief of the tool to occur during predetermined movements of the shoe support.

ERASTUS E. WINKLEY.

CERTIFICATE OF CORRECTION.

Patent No. 2,322,334.

June 22, 1943.

ERASTUS E. WINKLEY.

It is hereby certified that error appears in the printed specification of the above numbered patent requiring correction as follows: Page 23, first column, lines 68 and 69, claim 14, strike out "in the shank portion and rearward movement of the support when the tool is operating"; and that the said Letters Patent should be read with this correction therein that the same may conform to the record of the case in the Patent Office.

Signed and sealed this 9th day of November, A. D. 1943.

Henry Van Arsdale,
Acting Commissioner of Patents.
